CALCULATING MACHINE HAVING SHIFTABLE DIFFERENTIAL MECHANISM AND PRECONDITIONED TYPE - OF - OPERATION CONTROL MEANS

Herman Eldon Norris, Las Vegas, Nev., assignor to The National Cash Register Company, Dayton, Ohio, a corporation of Maryland

Filed Oct. 11, 1960, Ser. No. 62,050
25 Claims. (Cl. 235—60.25)

This invention relates generally to calculating machines and, more particularly, to improved mechanism thereof permitting a predetermined number of multi-cycle machine operations to be performed and enabling totalizer-contained amounts to be accurately read during both total and sub-total operations with item-entering digit keys retained in operated positions.

In the one particular embodiment of the present invention as herein illustrated and described, the calculating machine is a motorized version of the manual type of machine shown generally in the United States Letters Patent to Heber C. Peters Nos. 1,386,021 and 1,646,105, which issued, respectively, on August 2, 1921, and October 18, 1927, and in the United States Patent to Nelson White, No. 1,854,875, which issued on April 19, 1932. Reference may be had to these patents for a complete disclosure of machine mechanism which is not pertinent to the present invention and which, for that reason, will not be described or illustrated herein.

These typical machine constructions, as well as numerous other heretofore-known machines similar with regard to certain details of construction, such as, for example, that construction other than the multiple totalizer mechanism of United States Letters Patent No. 2,654,537, which issued on October 6, 1953, to Harry L. Lambert, are provided with a differential mechanism of the general type having totalizer-actuating means and printer-setting mechanism associated with and shifted selected distances in accordance with the longitudinal shifting of a plurality of stop bars. The stop bars, as set out in detail in the reference patents, are shifted first forwardly and then rearwardly, each machine cycle, to enable item amounts to be entered either additively or subtractively into the totalizer mechanism under some types of machine operations and enable accumulated amounts contained in the totalizer mechanism to be totaled or sub-totaled under other types of machine operations.

In accordance with such machine construction, and as fully set out in the above-mentioned reference patents, a desired item amount is entered either additively or subtractively into the machine by depression of digit keys representing that amount, which keys, prior to machine cycle initiation and the ensuing forward excursion of the stop bars, present abutments in the path of movement thereof to stop the bars at selected positions for causing, at the proper time during the machine cycle, the totalizer-actuating means to enter that amount into the totalizer mechanism. At the same time, a plurality of type bars are positioned for imprinting the entered item amount on a record material; that is, positioned in accordance with the shifting of the printer-setting mechanism along with the stop bars.

Also, as set out in detail in such prior patents, the total and sub-total machine operations are performed by permitting the stop bars to be shifted distances in accordance with the accumulated amount contained in the totalizer mechanism rather than distances as set by depressed or operated digit keys. With such construction, should a total or a sub-total machine operation be performed with digit keys operated for entering an item amount into the machine, the printer type bars would normally be positioned for imprinting, not the true accumulated amount

2

contained in the totalizer mechanism, but rather an amount representing the combination of the lower digits only of the two amounts. That is, such printing mechanism type bars would be set in accordance with the stopping of some stop bars by the totalizer mechanism and the stopping of other bars by digit key abutments before they have traveled their full extent of movement as permitted by the totalizer mechanism. Thus, it is seen that, during both total and sub-total operations of machines having the general construction illustrated and described in the above-mentioned representative patents, a true reading of the accumulated amount contained in the totalizer mechanism requires the digit key abutments not to lie in the path of movement of the stop bars, since such abutments represent not the accumulated amount, but rather an individual item amount as selectively set up on the digit keys; and, in accordance with the above description, to insure a correct reading of the accumulated amount contained in the totalizer mechanism, it has been the practice, as heretofore known, to require all digits keys to be returned to their unoperated positions prior to any attempt being made for performing either a total or a sub-total machine operation. This practice, as is well known in the art, presents the problem of having to reset the digit keys to their operated positions after the completion of each sub-total or total machine operation, even though such digit keys, as previously set to their operated positions, represent an item amount which, for reasons understood from later description hereof, is desired to be entered into the machine totalizer mechanism both before and after such sub-total or total machine operation. That is, in view of such typical machine construction, requiring all digit keys to be maintained in unoperated positions during totalizer-reading machine operations, an item amount may not be retained on the machine keyboard for, with intervening totalizer-reading machine operations, repeated entry into the machine totalizer mechanism. It is this problem which the present invention is designed to overcome, so that, as understood from later description hereof, a totalizer-reading machine operation may be now performed with digit keys retained in their operated positions, in turn permitting a reusable or what may be called a common factor type of item amount to be stored or memorized on the machine keyboard throughout a plurality of item-entering and intervening totalizer-reading types of machine operations. Hence, with the present invention, an item amount as initially set up on the machine digit keys, may be retained thereon and repeatedly entered into the machine totalizer mechanism, with intervening totalizer-reading operations taking place. Of course, each of such totalizer-reading operations will reflect the accumulated amount then contained in the machine totalizer mechanism, as affected by the previous item amount entered thereto.

Thus in view of such typical machine construction requiring digit-key-actuating abutments to not interfere with the stop bar movement during total and sub-total operations, and to overcome the heretofore-customary practice of requiring all digit keys to be therefore maintained in unoperated positions during such total and sub-total operations, it is the primary object of the present invention to provide new and unique mechanism enabling both the total and sub-total machine operations to be performed regardless of digit key positioning; that is, with digit keys maintained in either operated or unoperated positions.

A further important object of the invention is the provision of novel control mechanism enabling a predetermined number of multi-cycle machine operations to be performed for sequentially entering an item amount into the totalizer mechanism and then reading the accumulated amount contained therein during each machine operation.

Still another important object of the invention re-

sides in such mechanism permitting an item amount to be memorized or continuously stored by the digit keys throughout the predetermined number of multi-cycle machine operations, such item amount being entered either additively or subtractively into the totalizer mechanism during one part of each multi-cycle operation, and such item amount being retained on the digit keys as the affected accumulated amount is totaled or sub-totaled during the remainder of each multi-cycle operation.

A still further important object of the invention resides in means providing a single printing operation to be performed each multi-cycle machine operation for recording the totalizer-contained accumulated amount as affected by the item amount previously entered therein.

A still further important object of the invention resides in means for determining the sequence of machine functions to be performed during each multi-cycle machine operation.

With these and incidental objects in view, the invention includes certain novel features of construction and combinations of parts, a preferred form or embodiment of which is hereinafter described with reference to the drawings which accompany and form a part of this specification.

Of the drawings:

FIG. 1 is a fragmentary view in top plan of the forward portion of a calculating machine embodying the present invention;

FIG. 2 is a view in elevation of the left side of the machine, with the cabinet removed and with particular reference to that part of the mechanism which is located on the outside of the left vertical frame plate;

FIG. 3 is a view in elevation of the right side of the machine, with particular reference to that part of the mechanism located on the outside of the right vertical frame plate;

FIG. 4 is a view in side elevation of that portion of the machine mechanism which mainly is located on the inside of the right vertical frame plate;

FIG. 5 is a top plan view, looking down upon the base of the machine, showing part of the cycle initiating means, the machine cycle control mechanism, and part of the means enabling digit amounts to be stored during machine operations;

FIG. 5A is a detail in section of the machine structure taken on line 5A—5A in FIG. 5;

FIG. 5B is a detail, as seen from the right side in FIG. 5, of a guide frame permitting the differential stop bars to be shifted from item-entering positions to totalizer-reading positions;

FIG. 6, on the sheet containing FIG. 4, is a detail of a representative stop bar as positioned in alignment with digit key abutments during item-entering machine cycles, and as shifted away therefrom during totalizer-reading cycles;

FIG. 7 is a right side elevational view of the printer mechanism and paper carriage, partly in section, and with particular reference to type hammer and paper-shifting mechanism adjacent the center portion of the machine;

FIG. 7A is a detail of mechanism, as included in FIG. 7, for disabling the type hammers during item-entering cycles of the machine;

FIG. 7B is a view in top plan of that mechanism shown in FIG. 7A;

FIG. 8 is a view in rear elevation of paper spacing control mechanism, as included in FIG. 7;

FIG. 9 is a schematic representation of one line of elements incorporated in the machine cycle control mechanism, being illustrated at home position as seen from the right of the machine, and including a drive pawl as also illustrated in its home or rest position;

FIG. 10 is a view of the drive pawl shown in FIG. 9, as shifted to a neutral or unoperating position;

FIG. 10A is a view of said drive pawl of FIG. 9, as shifted to an operating position;

FIG. 11 is a view of additional cycle control mechanism associated with that of FIG. 9;

FIG. 12 is a right side elevation of the machine trip mechanism;

FIG. 13 is a schematic wiring diagram of the circuitry employed in the invention;

FIG. 14 is a detail in right side elevation and in partial section of certain parts of the totalizer mechanism of the machine, as interconnected with certain parts of the differential mechanism thereof;

FIG. 15 is a fragmentary portion of a typical printed record which may be prepared by the machine; and

FIG. 16 is a fragmentary portion of a further printed record which may be prepared by the machine.

General Description

As above mentioned, the typical calculating machine embodying the present invention, and as herein illustrated and described, is of the general type disclosed in United States Letters Patent Nos. 1,386,021; 1,646,105; 1,854,875; and, in part, 2,654,537. Referring to FIG. 1 herein, the mechanism of the machine is enclosed in a suitable cabinet or case 20 secured to a base member 21 which supports the framework of the machine. The machine is provided with a totalizer mechanism and may have, as seen in FIG. 1, associated indicator wheels 21, which are visible through a viewing aperture 22 provided in the case 20. As seen in FIG. 7, a paper carriage 23, extending across the rear of the machine in the usual manner and as set out in detail in the Heber C. Peters United States Patent No. 1,386,021, presents a platen 24, around which a listing tape (not shown herein) may be wound for receiving printed impressions of item amounts and other digits entered into the machine.

Referring further to FIG. 1, the machine is provided with a plurality of rows of digit keys 25, each row containing nine keys to represent the digits 1 to 9, inclusive; a cyclically-operable machine drive mechanism (FIG. 2), providing cycles of operation for item entry and accumulated amount reading or withdrawal; an add motor bar or control key 26 for initiating a cycle of operation in which an item amount set up on the digit keys 25 is entered additively into the totalizer mechanism of the machine; a correction key 27 for returning depressed digit keys 25 to an unoperated condition before the initiation of a machine cycle; and a total lever 28 (FIGS. 3 and 4), the forward shifting of which initiates a machine operating in which the amount accumulated in the totalizer mechanism is printed on the listing tape, while the rearward shifting of said lever 28 initiates a machine operation in which the accumulated amount is cleared from the totalizer mechanism along with being printed on the listing tape.

Although not specifically illustrated or described herein along with the representative embodiment of the present invention, but in accordance with the disclosures contained in the reference patents, a subtract mechanism of the general type as best shown in the Nelson White United States patent, No. 1,854,875, may be included for initiating a cycle of operation in which the item amount set up on the digit keys 25 is entered subtractively into the totalizer mechanism of the machine. Such mechanism, along with the mechanism associated with the add control key 26, permits item amounts set up on the digit keys 25 to be selectively entered either additively or subtractively into the machine totalizer mechanism.

In this regard, reference is also made to United States Letters Patent No. 2,665,063, issued to Nelson R. Friesberg and Oscar F. Larsen on January 5, 1954, which discloses a calculating machine of the general type which may also be included within the embodiment and scope of the present invention. Such a machine is similar in construction to those disclosed in the above-mentioned

Peters, White, and Lambert United States patents, having a differential mechanism of the same general type, having a slightly modified totalizer mechanism, and having individual total and sub-total control keys substituted for the single total lever 28 illustrated and described herein. A motor bar or add control key is included in such machine construction, being substantially the same as the control key 26 hereof, and, in view of the above-mentioned modified totalizer mechanism, as disclosed in the Frieberg and Larsen patent, a subtract mechanism of substantially different construction replaces that included in the illustration and description contained in the United States patent to Nelson White, No. 1,854,875.

Added to the basic machine employed in the present invention is a manually-settable machine operation control knob 29, shown in FIG. 1 as located adjacent the front end portion of the left side of the machine cabinet 20. Such control knob 29, through mechanism associated therewith as described later in the specification, provides means for selectively conditioning the machine to perform a predetermined number of multiple-cycle operations. That is, upon the turning of the knob 29 from a designated starting position, such as "0," to any desired digit position as inscribed thereon, mechanism associated therewith is set, and, after later machine cycling through cycle-initiating means, as will be shortly described, continuous multiple-cycle machine operations are performed, one after another, until the control knob 29 is automatically indexed back to its "0" position, at which time the cyclically-operable machine drive mechanism is permitted to come to rest. A pointer member 30, fixedly carried by the machine casing 20, cooperates with the control knob 29 for indicating at all times the number of continuous machine operations to be performed.

A continuous cycle control lever 31 is included in the machine construction as the means for initiating multiple-cycle machine operations in accordance with the setting of the knob 29. This lever 31, shown located in FIG. 1 to the left of the digit keys 25, when shifted rearwardly within a slot 32 in the machine case 20, becomes latched and causes the machine drive mechanism to be tripped for continuous cycling as long as the control knob 29 is away from its "0" position. Then, as the knob 29 returns to "0," as above set out, the lever 31 is released from its latched condition and permitted to shift forwardly within the slot 32, thereby releasing the machine drive mechanism from its continuously-tripped condition and permitting it to coast to its home or rest position, as seen in FIG. 2.

Referring further to FIG. 1, an additional control key 33 is included in the machine construction, being located a spaced distance forwardly of the lever 31, and providing means for selectively interrupting multiple-cycle machine operations initiated by the rearward shifting of the lever 31. Thus, with the provision of such a control key, hereinafter referred to as the stop control key 33, the predetermined number of continuous machine operations, as set up on the control knob 29, and as initiated by the lever 31, may be stopped at any time if so desired by the machine operator. Although the specific structure and precise mode of operation will be set out in detail later herein in reference to FIG. 2, it is sufficient to say at this time that such stop control key 33, when operated, also unlatches the lever 31 and permits the drive mechanism to thereby come to rest. Any remaining machine operations as set up on the control knob 29 may, of course, be resumed and completely by the mere shifting of the lever 31 again to its rearward, cycle-initiating position.

As will be later set out in detail in relation to FIGS. 4, 5, and 6, and as above included in the objects of the present invention, structure is provided in the machine construction enabling both total and sub-total machine operations to be performed with digit keys 25 retained in depressed conditions. Such structure, along with that per-

mitting a predetermined number of multi-cycle machine operations to be performed, provides an overall calculating machine extremely flexible in operation and with a wide range of available functions.

5 From the above general discussion of the invention, it
is seen that one desired embodiment thereof provides
for a calculating machine of the general type having ma-
chine drive means, totalizer mechanism, differential mech-
anism for entering digit amounts into and affecting ac-
10 cumulated amounts contained within the totalizer mech-
anism, means associated with and selectively setting the
differential mechanism in accordance with a digit amount
to be entered into the totalizer mechanism, machine multi-
cycle initiation and control mechanism, and mechanism
15 dissociating the differential mechanism from the setting
means in order that accumulated amounts contained in
the totalizer mechanism may be affected without disturb-
ing the digit amount setting means.

20 Although reference may be had to the above representative patents disclosing a calculating machine having the general construction embodied herein, enough of the pertinent mechanism thereof will be described in the following detailed description to give a thorough understanding of the instant invention.

Machine Drive and Cycle Initiating Mechanism

Referring to FIGS. 2 and 12, the calculating machine is driven by an electric motor 34 upon the closing of a switch 35, which connects the motor to a source of electric current (FIG. 13). The switch 35 is closed by a roller 37 on a lever 36, said lever 36 being rotatably mounted on a shaft 39 journaled in the machine left vertical frame plate 40, as seen in FIG. 2. Secured to the shaft 39, on the inside of the frame plate 40, is a multiple-armed lever 41, while on the outer side of the plate 40 there is secured to the shaft 39 a three-armed cycle control lever 45. These levers 41 and 45 are constantly urged clockwise by a spring 46, shown in both FIGS. 2 and 12, but are normally restrained from so moving by a trip latch 49. As seen in FIG. 12, this trip latch 49 is pivotally mounted on a stud 50, which extends from a bracket (not shown herein) secured to the frame plate 40. If the trip latch 49 is swung clockwise about its pivot stud 50, as seen in FIG. 12, by means to be described later herein, a distance sufficient to remove it from under a latch ear 42 of the lever 41, the shaft 39 and both levers 41 and 45 will likewise be turned clockwise under the force of the spring 46. During such clockwise movement, a stud 43, mounted on a lower extending arm of the lever 41, will strike the lower end portion of the lever 36 to turn it clockwise also, thus causing the roller 37 thereon to contact and close the switch 35, which completes the electric circuit (FIG. 13) for starting the motor 34.

As will be described shortly, the operation of the motor 34 causes a rear drive shaft 51 to oscillate first counter-clockwise and then clockwise back to its home position (FIG. 12) and in the reverse directions as seen in FIG. 2. A cam lever 52, secured to the drive shaft 51, normally holds a detent 53 away from an ear 38 turned from the upper end of the lever 36, toward which it is urged by a spring 54, but, as the cam lever 52 turns counter-clockwise upon the rocking of the drive shaft 51 (FIG. 12), a lower shoulder 55 of the detent 53 will fall behind the ear 38 as the lever 36 is moved clockwise, holding the switch 35 in a closed condition. Then the cam lever 52, on return movement at the end of the cycle, will strike a rearward end 56 of the detent 53, thereby lifting the detent 53 upwardly away from the ear 38 to again open the switch 35 at the end of the machine cycle.

70 The motor 34, through reduction gearing not shown herein, drives a horizontal shaft 58 counter-clockwise (FIG. 2). Secured to the shaft 58, behind a plate 59, is a notched gear or wheel 60, which is adapted to be engaged by the end of a pawl 61, such pawl 61 being 75 pivoted to a drive or crank plate 62, which is rotatably

7 mounted on the shaft 58. The pawl 61 is normally urged counter-clockwise into engaging position with the notched wheel 60 by a spring 63, but, when the cycle control lever 45 is in home position, a stud 47 thereon bears against an upper end portion of the pawl 61, as seen in FIG. 2, to hold it from such engagement with the wheel 60. Then, as above mentioned with reference to FIG. 12, if the trip latch 49 is rocked clockwise, permitting the levers 41 and 45 to be also rocked clockwise, the stud 47 on the lever 45 will be moved away from the pawl 61 and allow the pawl to engage the notched wheel 60 on the shaft 58. Thus, it is evident that, as the motor 34 is started, the pawl 61 is engaged with the wheel 60 on the shaft 58, and, due to its being mounted on the crank plate 62, the crank plate 62 commences to move counter-clockwise, as seen in FIG. 2. A drive link 64 is pivoted by one end to the crank plate 62 by means of a stud 65 thereon. The other end of the link 64 is pivoted to a bell crank lever 66, which is rotatably mounted on the rear drive shaft 51. Also pivoted to the drive link 64, by means of a stud 67, is a lever 68 having a roller stud 69 mounted near its outer end, which stud 69 cooperates with a notch in a drive plate 70 secured to the shaft 51. The stud 69 is normally urged into engagement with the notch by a spring 71 extending between the outer end of the lever 68 and a downwardly-extending arm of the bell crank lever 66. This spring 71 is strong enough to hold the stud 69 in the notch to form a driving connection between the bell crank lever 66 and the shaft 51 during all normal operations of the machine, but such connection will yield to any overload placed on the machine.

As the crank plate 62 nears the end of its rotation, a cam portion 72 thereof strikes a roller 48 carried by the downwardly and forwardly extending arm of the cycle control lever 45, rocking said lever 45 clockwise as seen in FIG. 2 and counter-clockwise as seen in FIG. 12. Referring further to FIG. 12, as the lever 45 is rocked counter-clockwise, it carries the lever 41 with it, thus allowing the trip latch 49 to swing under its ear 42 40 and hold it in home position. In this position, the motor switch 35 is open, since the cam lever 52 shifts the detent 53 from holding engagement with the lever 36, thereby permitting the leaf 35a of the switch 35 to rock the lever 36 counter-clockwise and under the detent 53.

The trip latch 49 is moved to machine-tripping position by an outer free end portion 76 of a trip lever 75 pivoted, adjacent its other end, by a stud 77 to a rear base plate 73 of the machine (FIG. 5). The actual tripping of a calculating machine embodying the present invention may be effected by various means; that is, the swinging of the trip latch 49 from under the ear 42 of the three-armed lever 41 as above described. Looking particularly to FIGS. 3 and 5, and referring to the above-mentioned United States patents to Lambert, No. 2,654,537, and Frieberg and Larsen, No. 2,665,063, it is seen that the machine may be effectively tripped upon the depression of the illustrated add motor bar or control key 26, or the subtract control key or lever if provided in the machine construction, through the following mechanism.

Referring to FIG. 5, the trip lever 75 is coupled to the add control key 26 by a link 78, interconnected to the lever 75 by a pivot stud 79 and extending therefrom toward the front of the machine. As seen in FIG. 3, the 65 forward end of the link 78 is pivoted to the lower extending arm of the machine main trip lever 82, pivoted to the machine right vertical frame plate 80 by a pivot stud 83. The forwardly extending arm of the main trip lever 82 has an ear 84, which is yieldingly held against the right frame plate 80 by a spring 85, thus urging the link 78 constantly rearwardly. In this position, under the tension of such spring 85, the lever 75 is in a non-tripping position and maintains the trip latch 49 under the ear 42 of the lever 41 (FIG. 12). In the manner set out 75

in detail in the above-mentioned patents to Lambert and to Frieberg and Larsen, upon the depression of a control key, such as the add motor bar 26 illustrated in this particular embodiment of the invention, the machine main trip lever 82 is rocked clockwise (FIG. 3) about the pivot 83 to overcome the tension of the spring 85, pulling the link 78 forwardly and rocking the trip lever 75 counter-clockwise. Upon such counter-clockwise rocking of the lever 75, the trip latch 49, which is normally urged in a latched position under tension of the spring 85, is swung to an unlatching position and permits the motor-activating switch 35 to be closed in the usual manner, as set out above in relation to FIG. 12. Then, after the machine cycles and the cam lever 52 removes the detent 53 from engagement with the lever 36, the trip latch 49 is again urged to latching position through a reverse rocking of the lever 75 under tension of the spring 85. In addition to such manual tripping of the machine under depression of the usual control keys provided thereon, the latch 49 may also be swung to a tripping position by means of electrically-controlled mechanism now to be described.

Referring further to FIG. 2, a link 86 is pivotally connected by one end to a downwardly-extending arm of the lever 45 by means of a stud 87, which also anchors, as shown in FIG. 12, the above-mentioned spring 46. The link 86 extends forwardly therefrom to have its other end pivotally interconnect, by means of a stud 88, an upwardly-directed lever 89, which is rockably mounted on a stud 91 carried by an extension member 40a of the left vertical frame plate 40. A finger member 90 is fixedly carried by and extends upwardly from the lever 89. With such construction, it is seen that, as the lever 45 is maintained in its unrocked position—that is, in the position shown in FIG. 2—when the machine drive mechanism is at home, the lever 89, through its finger member 90, maintains a current supply line switch 92 in a closed condition, such switch becoming open as the machine drive mechanism leaves home position and then again closing at the end of each cycle. As shown in FIG. 2, the switch 92 extends downwardly from a bracket 93, which is secured to the left vertical frame plate 40 at a zone above the lever 89.

A second switch 94, extending upwardly from the bracket 93, is normally open but may be closed by shifting an actuating roller 96 thereagainst. This roller 96, as seen in FIG. 2, is carried on the outer end of an arm 95, which, by means of a stud 97, is pivoted to and extends rearwardly from the above-mentioned continuous cycle control lever 31. Such lever 31, as seen in FIG. 2, is rockably carried on a frame-carried bolt 100, being normally urged clockwise thereabout by means of a spring 101 extending therefrom to a forwardly-positioned stud 102. Thus, as the lever 31 is manually shifted rearwardly within the slot 32 (FIG. 1)—that is, rocked counter-clockwise about the bolt 100, as seen in FIG. 2—the switch 94 is closed by the roller 96 being shifted thereagainst as the arm 95 is moved rearwardly, and, although various guide means may be provided for controlling the path of travel of the roller 96, in the preferred embodiment of the invention as illustrated herein, such guiding is performed by means of a frame-carried stud 98 slidingly engaging a longitudinal slot 99 provided in the arm 95.

Referring now to FIG. 5, upon such initial closing of the switch 94, a circuit is completed for energizing a trip solenoid 103, which, through inward shifting of its rearwardly-directed core member 104, rocks the trip lever 75 counter-clockwise about its pivot stud 77 to swing the trip latch 49 from under the ear 42 of the lever 41 (FIG. 12). Upon this happening, the motor switch 35 is then closed by the roller 37 as above described, thus starting the motor 34 in operation. As illustrated in FIG. 5, the trip solenoid 103 is secured to the rear base plate 73 of the machine, having the outer end of its core member 104 pivoted to the trip lever 75 at a zone approxi-

mately central of the outer free end 76 and the link stud 79 thereof.

As seen in FIG. 13, wherein the circuitry illustrated is that as effected when the calculating machine is at home, or rest, position, an additional switch 103a is included in the trip-solenoid-energizing circuit, being associated with machine cycle control mechanism which will be described in detail later in this specification. At this time, it is sufficient to say that such switch 103a is maintained in a closed condition by such mechanism when the calculating machine is at home position; that is, not in the process of performing a multiple-cycle operation as later described.

From the above description, and in view of the circuitry illustrated in FIG. 13, it is seen that the calculating machine embodying the present invention may be cycled for operation in several ways. In the one instance, the motor bar 26 may be depressed for manually rocking the trip lever 75 as above described. In the other instance, the lever 31 may be shifted rearwardly within the slot 32 (FIG. 1) for closing the switch 94 and completing a circuit to the trip solenoid 103, which, as above described, also rocks the trip lever 75. In each instance, the rocking of the trip lever 75 causes the trip latch 49 to be removed from under the ear 42 of the lever 41, thereby permitting the motor switch 35 to be closed for starting the motor 34 in operation and oscillating the rear drive shaft 51 as above described. Referring especially to FIGS. 2 and 13, although the switch 94 may be maintained in a closed condition, either by manually holding the lever 31 in its rearwardly-shifted position or through automatic latching means as will be later described in relation to the multiple-cycle control mechanism, the energizing circuit is removed from the trip solenoid 103 upon the closing of the switch 35, since, simultaneously therewith, the switch 92 becomes opened as the machine drive mechanism moves from its home position.

As above mentioned, the drive shaft 51, which extends transversely between the machine frame plates 40 and 80, oscillates first counter-clockwise and then clockwise (FIGS. 3 and 4) during each machine cycle. Referring especially to FIG. 3, adjacent the frame plate 80, the rear drive shaft 51 has secured thereto a plate-like member 105, connected by a link 106 to the usual full-stroke sector 107 secured to a main shaft 108. The main shaft 108 also is mounted in the frame plates 40 and 80 for oscillating movement therein at a zone forward of the rear drive shaft 51.

The plate-like member 105 (FIG. 3) has, in its forward edge, a depression into which a roller 109 is urged by a spring 111. The roller 109 is carried by a bell crank 110, which is pivotally mounted on the frame plate 80. The notch or depression is so located in the member 105 that it will be positioned opposite the roller 109 when the member is in its normal, home, position, thereby cooperating with the roller 109 in assisting parts of the machine to be restored to their normal, home, positions.

Machine Keyboard

The machine is provided with a suitable keyboard in which the digit keys 25 for controlling the movement of the differential mechanism are mounted. The keyboard is of the well-known type upon which digit amounts may be set up to control the entries of amounts into the machine, being fully shown and described in United States Letters Patent to Charles Schroder No. 2,062,731, which issued December 1, 1936, and to which patent reference may be had for the specific details of its construction.

For an understanding of the instant invention, it is only necessary to explain that the keyboard is made up of the plurality of rows of digit keys 25, one row of which is shown in FIG. 4, which keys are normally out of controlling relation with the differential mechanism and

which, when they are selectively depressed to set up amounts to be entered into the machine, are moved into position to control the extents of movement of the differential mechanism according to these amounts. In general, the keyboard construction includes a top plate 115, a bottom plate 116, a left side plate 117 (FIG. 2), and a right side plate 118 (FIGS. 3 and 4). The digit keys 25 are provided with key stems 25a, slidably mounted in aligned slots cut in the top and bottom keyboard plates, being normally yieldingly held up in ineffective positions by means of springs (not shown herein) and projecting below the bottom plate 116 as digit keys 25 are depressed for entering item amounts into the machine. As will be described later in detail, such projecting key stems 25a control the movement of the differential mechanism and its associated printing mechanism.

As also set out in detail in the Schroder United States Patent No. 2,062,731, the usual zero stop bail and latching bail are included in the keyboard construction, the latter of which bails latches any depressed digit key 25 in operated condition until it is released, prior to a machine cycle, by depression of another digit key in that row or by the clockwise rocking of a key release bail 120 (FIGS. 3 and 4). Although several means are normally provided in machine constructions for so rocking the key release bail 120, including the usual by-pass pawl of the Schroder United States patent, which causes all digit keys to be released near the end of each machine cycle, the sole means incorporated herein for rocking the bail 120 is the above-mentioned manually-operable clear or correction key 27. As fully disclosed in the Heber C. Peters United States Patent No. 1,386,021, such key 27, when depressed, engages a stud 121 of the bail 120, thereby rocking the bail 120 and releasing the keys in the usual manner. This single means for actuating the key release bail 120 seems self-evident when considering the overall scope of the present invention, wherein, as above described, each digit amount is desirably maintained or "stored" on the machine keyboard throughout a plurality of multiple-cycle operations.

Differential Mechanism

The differential mechanism used in the present invention is substantially like that fully shown and described in the United States Patent to Nelson White No. 1,854,875 and will, therefore, be but briefly described herein. In such construction, a differentially-operable means is provided for each denominational row of digit keys 25, and, since all of these means are substantially alike, it is believed that an understanding of the construction and operation thereof will be clear from the following description of a typical one of them only.

As shown in FIGS. 4 and 6, a stop bar 122 is located immediately below each row of keys 25. This stop bar 122 is pivotally connected at its rear end by a stud 123 to a diverging lever 126 and is supported by a slotted plate or comb 128 at its forward end so as to be suitably guided for sliding movement. A spring 124, which is connected between a stop bar stud 125 and a forward cross-shaft 129, normally urges the stop bar 122 forwardly of the machine; that is, to the left as seen in FIG. 4. When the machine operates, the stop bar 122 will be allowed to be moved to the left or forwardly of the machine by the spring 124 until one of the abutments on the upper edge of the bar engages the lower end of the stem 25a of a depressed key 25 to limit the movement of the stop bar 122 to an extent which corresponds to the value of the depressed key.

The diverging lever 126 is pivotally mounted on a diverging lever shaft 127 and has a rearward extension to which is connected an amount printing type bar 130. As the stop bar 122 moves forwardly of the machine, the diverging lever 126 will move therewith, being rocked counter-clockwise (FIG. 4) about the shaft 127 a distance proportional to the value of the depressed key, and will position the type bar 130 accordingly to place in

printing position the type corresponding to the depressed key.

As further set out in the Nelson White United States Patent No. 1,854,875, a rack lever 351 is also pivotally mounted on the shaft 127 (FIG. 4), immediately adjacent the diverging lever 126 (FIG. 6). As illustrated (FIGS. 4 and 6), the construction of these diverging and rack levers 126 and 351 is somewhat different from that employed in the White machine, in that both the gooseneck arm and the extension thereof are herein eliminated. The rack lever 351, as further illustrated in FIG. 14, carries at its upper end a totalizer-actuating rack 352 associated with the usual totalizer mechanism, which is also described only briefly herein in view of the prior disclosure thereof in both the Peters Patent No. 1,386,021 and the White Patent No. 1,854,875. By means of an intervening hub 350 (FIGS. 4, 6, and 14), the rack lever 351 is permanently joined to the diverging lever 126 and moves therewith to effect the totalizer mechanism in accordance with the movement of the stop bar 122 as above described.

This interconnecting of the rack lever 351 with the diverging lever 126, as specifically set out in the White Patent No. 1,854,875, results in an overall diverging lever substantially the same as the original diverging lever of the standard Peters adding machine, being a unitary member, as disclosed in the Peters Patent No. 1,386,021. With such construction, when the diverging lever 126 rocks counter-clockwise (FIG. 4) about the shaft 127 as the stop bar 122 moves forward to contact a depressed key 25, the rack lever 351 and its associated rack 352, which are joined thereto (FIG. 14), will be given a similar movement.

The diverging lever 126, its permanently interconnected rack lever 351, and the stop bar 122 are normally held in their home positions, shown in FIG. 4, by means of the usual bail 131, which engages the upper front edge of the diverging lever 126 (see also FIG. 14). The bail 131 extends across the machine and, as shown fully in FIG. 14, is supported at its ends by the usual bail pair of arms, which are operated to move the bail forward an amount sufficient to allow the maximum extent of setting movement of the diverging lever 126 during the first half of a machine cycle, and which return the bail and the lever 126 to the position shown in FIG. 4 during the last half of a machine cycle, as is well known in this type of machine.

In the operation of the differentially-operable means, therefore, the diverging lever, the rack lever, and the stop bar will move with the bail 131 until one of the abutments on the stop bar 122 engages the lower end of a key stem 25a to prevent its further movement, after which the bail 131 leaves the upper front edge of the lever 126 and continues its movement. In its return movement, the bail 131 picks up the diverging lever 126 and the rack lever 351 from their set positions and carries them and the stop bar 122 with it back to their normal positions, as shown in FIG. 4.

As above described, the stop bar guide plate or comb 128 extends across the forward end of the machine to its position and guide each stop bar 122 in relation to its associated row of digit keys 25. Looking at FIGS. 5, 5A, and 5B, such comb 128 is carried by a rearwardly and upwardly-directed leg of a supporting frame 132 and fixedly extending between the machine frame plates 40 and 80, and, by means of a plurality of comb-carried and frame-carried studs 134, said comb 128 is enabled to be shifted leftwardly, as seen in FIG. 5, a set distance along its supporting frame 132. An overturned flange 135 is provided adjacent each end of the frame 132, extending over the upper edge portion of the comb 128 for maintaining a close relationship between the fixed frame and the shiftable comb.

Although the precise means for shifting the comb 128 along its frame 132 will be described later in the specification,

in more or less detail, particularly in reference to the machine multi-cycle control mechanism, it is sufficient to say at this time that such control mechanism, through a cam member, an arm, and a link, periodically shifts the comb 128 from its solid-line position of FIG. 5 to its dash-line position thereof, and then returns it back to its starting position during designated machine cycles. As best seen in FIG. 5, this arm, herein designated as control arm 136, is pivotally mounted on a base-carried bracket 139 by means of a bolt 140. A rearwardly-positioned roller stud 137 thereof operably engages said cam member, while a forwardly-positioned stud 138 thereof pivotally connects one end of the above link, herein designated as control link 141, which in turn pivotally interconnects at 142 the lower right end portion of the comb (FIG. 5B). With such construction, as the machine multi-cycle control mechanism cam member is rotated during machine cycles of operation as later described in the specification, the stop bar guide plate or comb 128 is effectively shifted first leftwardly by the cam member and then returned thereby to its starting position; that is, to the solid-line position of FIG. 5.

Referring further to FIG. 5, it is apparent that, as the comb 128 is so shifted back and forth along the supporting frame 132, the plurality of stop bars 122 guided thereby, one for each row of digit keys 25, must likewise be shifted therewith. As seen in FIG. 6, where a typical stop bar 122 is illustrated in relation to its diverging lever 126 and guiding comb 128, such shifting of each stop bar is permitted in view of the normally loose pivotal interconnection between its rear end and the associated diverging lever; that is, such stop bar rear end being loosely mounted on the diverging lever stud 123. Therefore, in accordance with such construction, as the comb 128 is actuated from its home position, which is the solid-line position of FIGS. 5 and 6, to its shifted, or dash-line position thereof, the forward end of each stop bar 122 is shifted a like distance, which, as seen in FIG. 6, is sufficient to remove its upstanding abutments from under the associated row of digit keys 25. Then, upon the return shifting of the comb 128 to its home position, each stop bar 122 is again shifted back to lie immediately below its row of digit keys 25. Although the extent of forward movement of each stop bar 122 is controlled by an operated digit key 25 located thereabove when in its home position, each stop bar 122 is not affected by that depressed or operated digit key 25 when in its shifted position and may, therefore, travel an extent wholly independent of a digit key 25 which may be retained in its operated or depressed condition.

Totalizer Mechanism

As mentioned above, the totalizer mechanism of the instant invention is substantially like that illustrated and described in the Peters and White patents, to which reference may be had for a most complete understanding of its construction and mode of operation.

Essentially, the totalizer mechanism is carried across the upper portion of the machine, having its previously-mentioned indicator wheels 21 (FIG. 1) rotatably carried by a shaft-like rod 353, which rod, as seen in FIG. 14, is part of a number wheel frame 354, and which frame, as further seen in FIG. 4, is carried by a rock shaft 355 extending between the machine frame plates 40 and 80. In the usual manner, as set out in detail in the Peters Patent No. 1,386,021, the number wheel frame 354 is made up of a plurality of interconnected partition and end plates, and, through the selected rocking of a machine type of operation lever (not illustrated herein), is caused to be moved upwardly and downwardly at a precise time during machine cycling. As further seen in FIG. 14, each totalizer-actuating rack 352 is adapted to mesh with a totalizer pinion 356, which is secured to a related one of the indicator wheels 21. Associated with such rack 352 and pinion 356 are the custom-

ary transfer and control mechanisms, being supported in the usual manner on shaft-like rods 143 and 144, extending between the machine frame plates 40 and 80 (FIGS. 2, 4, and 14).

With such overall construction, which, in view of the Peters and White reference patents, is well known to those skilled in the art, it is understood that either clockwise or counter-clockwise rotation may be imparted to the totalizer pinions 356 through each rocking of the diverging levers 121 and their interconnected rack levers 351, depending upon both the point of time at which and the length of time for which such pinions 356 are caused to mesh with the actuating rack 352, as controlled by upward and downward rocking of the number wheel frame 354 during machine cycling. Thus, through rocking of the number wheel frame 354, as directed by both digit-entering and reading operations of the instant machine, the totalizer mechanism is actuated by the above-mentioned rack levers 351 associated with the diverging levers, receiving item amounts therein when the stop bars 122 are set in accordance with operated digit keys 25 and giving accumulated amounts therefrom when such stop bars 122 are set in accordance with the totalizer mechanism itself, the latter of which requires all digit keys 25 to be in ineffective positions in relation to the stop bars 122.

Printing Mechanism and Record-Feeding Means

Printing is performed in the instant machine by the well-known printer as illustrated in the above-mentioned United States reference patent to Harry L. Lambert, No. 2,654,537, and as set out in detail in United States Letters Patent to Nelson R. Frieberg and Oscar F. Larsen, No. 2,813,611, which issued on November 19, 1957.

As above mentioned in reference to the differential mechanism, a rearwardly-extending portion of the diverging lever 126 is pivoted to the type bar 130. As seen in FIG. 7, this type bar 130 is movable vertically in slotted guides 148 and 149 with respect to the paper platen 24, and in accordance with the selected positioning of the diverging lever 126 under control of the associated stop bar 122. The type bar 130 has, at its top portion, a plurality of individual type members 159. When a particular type member 150 is moved to a printing position, it is hit by a printing hammer 151 when released from a cocked position, at printing time, by the tripping of a latch 152.

Referring to FIG. 7, when the type bar 130 is selectively raised to printing position as above described, a stud 147 thereon enables an interponent 153 to rock counter-clockwise on a bail 154 under urge of a spring 155. The bail 154 is secured between an arm 156 and another arm, like the arm 156, secured on a shaft 157, which extends between the printer vertical side plates 145 and 146 (FIG. 7B). A cam lever 158, secured on the rear drive shaft 51, is also rocked first counter-clockwise and then clockwise during each machine cycle. With such counter-clockwise rocking of the cam lever 158, a stud 159 thereon strikes the tail 160 of the arm 156, shifting the bail 154 and the rocked interponent 153 toward a lower step of the hammer latch 152, which thereby is moved to unlatching position near mid-cycle of a machine operation. As seen in FIG. 7, such actuation of the hammer latch 152 is permitted if, and only if, the type bar 130 has been moved from home by its diverging lever 126, so as to shift its stud 147 and render the interponent 153 effective for causing the printing hammer 151 to hit the type member 150 which is positioned at the printing station. Should the type bar 130 not be moved from its home position by the diverging lever 126, it is clear that the interponent 153 will not be permitted to rock counter-clockwise for actuating the hammer latch 152 when shifted, as above described, by the cam lever stud 159.

Referring further to FIG. 7, along with FIGS. 7A and 7B, additional structure is included in the printer mechanism for normally disabling a printing operation even though the type bar 130 is moved from home by the di-

verging lever 126 and the interponent 153 is thereby permitted to rock, as above described, toward the lower step of the hammer latch 152. This included structure, as will now be described, effectively controls the extent of 5 rocking of the interponent 153 after it has been released for rocking by the shifting of the type bar 130. That is, when once released for rocking, the interponent 153 may still be allowed a limited rocking only, insufficient to engage the lower step of the hammer latch 152 and thereby not rocking such latch 152 as the interponent is shifted during a machine cycle.

As best seen in FIGS. 7 and 7A, a print bail 161 is rockably carried by a shaft 165 extending between the machine frame plates 40 and 80, such bail 161 being normally urged counter-clockwise by means of a spring 164. A left arm member 162 is turned rearwardly therefrom to slidingly engage, by means of a bifurcated end portion, a stud 167 carried on the upper end of a bell crank 166 rockably mounted on a second shaft 169. As seen in FIGS. 2 and 3, this shaft 169 extends between the frame plates 40 and 80. A second arm member 163 (FIG. 4), turned rearwardly and somewhat downwardly from the right end of the bail 161, will be described later herein in relation to bail-actuating means associated with the 20 multi-cycle control mechanism of the machine. To provide a more thorough understanding of the approximate location of members now being described, it may be stated that the bail right arm member 163 lies near the machine right frame plate 80, whereas the bail left arm member 162 and its associated bell crank 166 are located adjacent the outer side of the printer left vertical side plate 145 (FIG. 7B).

Referring further to FIG. 7A, a link 170, by means of a bell crank stud 168, is pivotally interconnected by one 35 end to the bell crank 166. The link 170 extends downwardly therefrom to likewise pivotally interconnect, through a stud 171, the forward end of a print control arm 172, which is rockably mounted on the left end of a printer shaft 175, also located on the outer side of the printer left vertical side plate 145. A second bail member, herein referred to as a print control bail 176, is rockably mounted on a second printer shaft 180 and is so positioned thereon, between the printer side plates 145 and 146, to extend immediately below the forward end 40 portion of each interponent 153. By means of an outwardly-directed stud 178, carried by an upwardly- and rearwardly-turned arm portion 177 of the bail 176, such bail is operably interconnected with the print control arm 172 and its associated link 170, bell crank 166, and bail 161. Although not specifically illustrated herein, the stud 178 extends freely through an opening in the printer left vertical side plate 145 to slidingly engage, as shown in FIG. 7A, a slot 173 in the rear end portion of the print control arm 172. A spring 179, stretched between 45 a control arm stud 174 and a side frame stud (not shown herein), normally urges the print control arm 172 counter-clockwise, and, in view of the above-described stud 178 and slot 173 interconnection, the print-blocking bail 176 is thereby, likewise, normally urged in the same direction. When so positioned, the bail 176 prevents sufficient 50 rocking of the interponents 153 for actuating the hammer latches 152 as above described. This is best illustrated in FIG. 7, wherein such bail 176 is illustrated as operably associated with the usual printer mechanism. Referring 55 thereto, it is seen that each interponent 153, when released for rocking by its type bar 130, is permitted a slight rocking movement only before contacting and being stopped by the bail 176. This movement, the extent of which is herein illustrated by the dash-line position of the interponent as stopped by the bail, is less than that required for engaging the lower step and actuating the trip latch 152 as above described.

Thus, in the normal, spring-urged position of the bail 176, as seen in FIGS. 7 and 7A, the printing operation is 60 effectively prevented during each machine cycle. On the 65

other hand, and in accordance with such mechanism disclosed herein, the printing operation may be performed by overcoming such normal positioning provided by the tension of the spring 179. In this regard, it is apparent that, as the bail 161 is rocked clockwise about its pivot shaft 163, the bell crank 166 will be thereby rocked counter-clockwise about its pivot shaft 169, and, through the shifting of the link 170 thereby, the print control arm 172 will be rocked clockwise about its pivot shaft 175. Upon this happening, the print control bail 176 will likewise be rocked clockwise about its pivot shaft 180, being thereby removed from its normal blocking position and permitting the interponent 153 to rock the distance required for tripping the hammer latch 152 when it is shifted forwardly, as above described, during the machine cycle. As above mentioned with reference to the second arm member 163 of the bail 161, specific means for rocking the bail 161 and causing a printing operation to be performed will be described later herein.

Referring further to FIG. 7, it is seen that the record feed mechanism of the instant invention is substantially the same as that disclosed in the above-mentioned United States Letters Patent to Nelson R. Frieberg and Oscar F. Larsen No. 2,813,611. Pivoted to the paper carriage left side plate 182 is an arm supporting the left end of a vertical feed bail 185. The right end of the feed bail 185 is supported by a second arm, like the arm 183 illustrated herein by dash lines, pivoted to the paper carriage right side plate. The feed bail 185 is biased to swing clockwise about its pivots by a spring 186 wound around the pivot of the second arm 183 and hooked over the bail. Pivoted to a centrally-disposed frame-supported member 187, by means of a pin 188, is a yoke 189, supporting a roller 190 and having a forwardly- and upwardly extending arm portion 191. The outermost end of the arm portion 191 rests against the stud 159 of the cam 158 secured to the machine rear drive shaft 51.

When the machine is at home, the roller 190, which constantly bears on the forward edge of the feed bail 185, keeps the feed bail rocked to its counter-clockwise position. As the machine operates, the rear drive shaft 51 moves the cam 158 and its stud 159 away from the arm portion 191, thereby enabling the bail 185 to rock clockwise unless otherwise prevented. As also seen in FIG. 7, the upper end portion of the arm 183 has pivoted thereto, at 193, a record feed pawl 192, which is held rocked by a spring 194 to normally abut a stud 195. A forward toothed end of the feed pawl 192, when the machine is at rest, or home, nearly engages a ratchet wheel (not shown herein) secured to the right end of the platen support shaft 24a. Therefore, as the machine commences operation and the feed bail 185 moves toward the machine rear drive shaft 51, the feed pawl 192 is drawn rearwardly, and, on the last half of the machine cycle, such pawl 192 moves forwardly to contact a tooth on the ratchet wheel and move it, along with the platen 24, coupled thereto, in a vertical record-feeding direction.

In the preferred embodiment of the present invention, normally there is positioned in front of the yoke arm member 191 an arm 196 for blocking the feeding movement of the vertical feed bail 185, such arm 196 being illustrated in FIG. 8 as extending upwardly from a pivot bolt 197 secured to a plate member 198, which extends across the lower rear end of the machine. A link 199, by means of pivot studs 200 and 201, operably connects the arm 196 to a bell crank 202, which, by means of a bolt 205, is rockably mounted adjacent the right end of the machine plate member 198. In view of such construction, if the bell crank 202 is rocked counter-clockwise about its pivot bolt 205, the arm 196 is rocked clockwise about its pivot bolt 197, thereby being removed from in front of the yoke arm portion 191, as illustrated by the dash lines in FIG. 8, and permitting the record material to be vertically spaced as above described. As will be described later herein, means is provided for selec-

tively rocking the bell crank 202 during multi-cycle machine operations.

Machine Cycle Control Mechanism

Referring again to FIG. 2, upon machine cycling being initiated by the rearward shifting of continuous cycle control lever 31, thereby closing the switch 94 and energizing the trip solenoid 103, unique control mechanism of the present invention is conditioned for causing a three-cycle machine operation to be performed. In this regard, and in accordance with the preferred embodiment of the invention, the first cycle may be termed an add cycle for entering the item amount, as set up on the digit keys 25, additively into the totalizer mechanism; the second cycle may be termed a non-add cycle for conditioning the machine mechanism for a totalizer reading operation; and the third cycle may be termed a sub-total cycle for reading and printing the amount contained in the totalizer mechanism. Of course, the first and third cycles, above referred to as being preferably add and sub-total cycles, may conveniently be changed, respectively, to subtract and total cycles if so desired for a particular application of the machine. In any event, such three cycles constitute one machine operation, and, in view of the control knob 29 with its associated mechanism, as will be described shortly, a predetermined number of such three-cycle machine operations may be easily and accurately provided.

As the lever 31 is shifted rearwardly for closing the switch 94, a stud 206, carried by the lower end thereof, is shifted forwardly to a position behind an upper shoulder 209 of a switch latch 207. The latch 207 is rockably carried, by means of a pivot stud 211, on the left vertical frame plate 40 of the machine, having its major length 208, including the shoulder 209, extending rearwardly of the pivot stud 211, and its minor length 210 extending forwardly and upwardly therefrom. A spring 213 extends between the outermost end of the length 208 and the upper positioned frame stud 98 to yieldingly urge the latch 207 clockwise and in constant abutment with the stud 206. Thus, when the lever 31 is shifted rearwardly a distance sufficient to close the switch 94, its stud 206 will fall behind the shoulder 209 of the latch 207, thereby automatically retaining the lever 31 in its shifted position and maintaining the switch 94 in a closed condition. Such latching of the lever 31 is retained until the normal tension of the spring 213 is overcome and the latch 207 is rocked counter-clockwise to remove the shoulder 209 from in front of the stud 206, at which time the spring 101 returns the lever 31 to its unoperated or forward position.

As mentioned earlier in the specification, the stop control key 33 provides one means for unlatching the lever 31 from its operated position. Such key includes a downwardly-extending stem portion 214 slidably guided for approximately vertical movement by means of an upper, key-frame stud 119 slidably engaging a slot 215 therein, and a lower, machine-frame plate stud 218 slidably engaging a bifurcated end portion thereof. A spring 219, extending between a stud 216 of the stem 214 and the stud 119, yieldingly retains the stop control key 33 in an upper, unoperated, position, being overcome upon the depression of the key 33 and permitting a lower stud 217 thereof to move downwardly a distance determined by the slot 215 provided therein. This movement of the stud 217 is sufficient to enable it to contact and rock the latch 207 counter-clockwise an amount which permits the lever stud 206 to be released therefrom, whereupon the lever 31 is immediately returned to its unoperated position under the urge of the spring 101. Also included in the present invention is a second means for unlatching the lever 31 from its operated position, being associated with and actuated by the cycle control mechanism as now described.

Referring to FIG. 2, a link 226, extending between pivot studs 221 and 222, operably connects the continuous

cycle control lever 31 with a forwardly-positioned arm 223. This arm 223 is secured to a shaft 224, herein shown as being secured to the outermost end thereof and on the outer side of the machine left frame plate 40. As best seen in FIG. 5, the shaft 224 extends inwardly from the plate 40 to terminate at approximately the center of the machine, being journaled between such plate 40 and an ear 74a turned upwardly from a machine forward base plate 74. A second arm 225 is secured to the shaft 224, adjacent the base plate ear 74a, and, by means of a link 226, as best seen in FIG. 9, extending between pivot studs 227 and 228, the shaft 224 is operably interconnected with an arm 229, which, in turn, is secured to a rearwardly- and upwardly-positioned rock shaft 230. As seen in FIG. 5, the rock shaft 230 is journaled between a pair of spaced-apart, upstanding brackets 231 and 232 fixedly carried by the base plate 74. A second arm 233 is also secured to the rock shaft 230, herein shown as being spaced a distance from the arm 229 to position an upper stud 234 thereof immediately below and normally in the path of travel of a cam shaft drive pawl 235 (FIG. 5). The drive pawl 235, as best seen in FIGS. 4 and 5, extends forwardly from an arm 240 secured to the machine main shaft 108, being pivotally connected thereto by a stud 236, so that, as the shaft 108 is oscillated during each machine cycle, the pawl 235 is thereby shifted first forwardly and then returned rearwardly, back to home.

Referring further to FIG. 5, a cam shaft 242 is likewise journaled between the brackets 231 and 232, being located approximately centrally of the horizontal distance between the shafts 224 and 230 and slightly upwardly of the shaft 230 (FIG. 4). Fixed to the cam shaft 242, adjacent its right end, is a drive member 243, which, when permitted to be actuated by the drive pawl 235, aligned therewith and positioned thereabove as seen in FIG. 5, causes the cam shaft 242 to be rocked clockwise (FIG. 4) a predetermined distance during each machine cycle. This rocking of the cam shaft 242 is best understood by looking to FIG. 9, wherein the various members secured to the cam shaft 242 are illustrated in side-by-side relationship, and in their respective home positions, as viewed from the right of the machine.

Referring to FIG. 9, and also to FIGS. 10 and 10A for detail reference numerals not included in FIG. 9 for the sake of clarity, the illustrated drive member 243 comprises a pair of spaced-apart side plates 244 and 245, firmly secured one to another by means of three intervening studs 246, 247, and 248. These three studs, hereinafter referred to as indexing studs, are equally spaced, one from another, around the peripheries of the plates 244 and 245. As also seen in FIG. 9, the drive pawl 235 is provided with a forward end portion 237, having a lower, cam-like surface terminating in a downwardly-directed shoulder 238. By means of a spring 241, stretched between the pawl 235 and the base plate 74, the pawl 235 is yieldingly urged counter-clockwise (FIG. 4) to present its forward end portion 237 normally in operable association with the drive member 243. In this instance, and when the machine is at rest, the pawl end portion 237 is located immediately behind one of the indexing studs, such as the stud 247, with its shoulder 238 abutting the next stud therebehind, such as the stud 246, as seen in FIG. 9, where the cam shaft 242 is illustrated in its unrocked, or home, position. As further seen in FIG. 9, a downwardly-extending cam surface 239 is provided on the pawl 235, being located behind the rock shaft stud 234 when the machine is at home and shifted substantially therewith during each machine cycle.

In considering the cycle control mechanism thus far described, it is seen that, when a machine operation is initiated by means of the continuous cycle control lever 31, the cam shaft 242 is effectively rocked one third of a revolution (120 degrees) during each machine cycle

thereof. Referring to FIG. 2, when the lever 31 is shifted rearwardly, as above described, the forward shaft 224 is thereby caused to be rocked clockwise (FIG. 2) and counter-clockwise (FIG. 9), which shaft 224, in turn, causes the rock shaft 230 to be rocked clockwise (FIG. 9) for removing the stud 234 from the path of travel of the cam line drive pawl 235. As best seen in FIG. 10A, such stud 234 is rocked downwardly and away from the drive pawl cam surface 239, enabling the drive pawl forward end portion 237 to engage the next forward indexing stud, when the pawl 235 is shifted forwardly during the first half of the machine cycle, and rock that stud, along with the shaft 242, clockwise, as the pawl 235 is returned home during the last half of the machine cycle. In accordance with the specific illustrations of FIGS. 9 and 10A, during the forward shifting of the drive pawl 235, its forward end portion 237 is cammed over the indexing stud 247, enabling the shoulder 238 to be yieldingly urged therebehind. Then, upon the return shifting of the pawl 235, such shoulder 238 carries with it the stud 247 and positions it at the zone formerly held by the stud 246. Such movement of the stud 247 causes the cam shaft 242 to be indexed 120 degrees. In view of the latching of the control lever 31, as above described, this cam-shaft-indexing operation is continued during each machine cycle provided in the overall machine operation as initiated by the lever 31.

Contrary to this operation, when a machine cycle is initiated by some means other than the lever 31, as by the add control key 26 provided in the instant invention, the cam shaft 242 remains stationary; that is, it is not rocked by the drive pawl 235 as described above. In this instance, the rock shaft stud 234 would remain positioned, as seen in FIGS. 9 and 10, in the path of travel of the drive pawl cam surface 239. With such positioning of the stud 234, as the drive pawl 235 is shifted forwardly during the first half of the machine cycle, its under surface 239 soon contacts such stud 234, thereby camming the pawl also upwardly (FIG. 10) and preventing its forward end portion 237 from engaging the stud 247. Then, upon the return shifting of the pawl 235, its forward end portion 237 again assumes its normal, home position, adjacent the stud 246 (FIG. 9). As seen in FIGS. 5 and 9, a roller 249, on the machine shaft 129, cooperates with an upper cam surface 250 of the drive pawl 235, assuring a true home positioning of such pawl when the machine is at rest. The shaft 129, as seen in FIG. 5, is journaled between the machine left frame plate 40 and the base plate carried bracket 231, being located (FIG. 4) rearwardly and upwardly from the rock shaft 230.

Secured to the cam shaft 242, adjacent the drive plate 243, is a drum cam 251. This cam, as best seen in FIG. 5, is provided with the usual raceway, herein receiving continuously the above-mentioned roller stud 137 of the control arm 136 and providing the means for periodically rocking the arm 136 first clockwise, for shifting the stop bars 122 from under their respective rows of keys 25, and then counter-clockwise, for returning the shifted stop bars back to their home positions, underlying such rows of keys 25. As will be described later with reference to the machine operation, such cam and control arm arrangement causes the stop bars 122 to be shifted away from the keys 25 near the end of the second, or non-add, cycle of each machine operation, there being three cycles within each operation as above described, and likewise causes such stop bars to be returned immediately under the keys 25 near the end of the third, or sub-total, cycle of each operation. With such arrangement, it is seen that the stop bars 122 are positioned under their respective rows of keys 25 during the first, or add, cycle of the machine operation, thereby entering the set-up amount into the machine totalizer mechanism during such cycle.

Adjacent the cam 251, and to its left, the cam shaft 242 carries three plate cams 252, 253, and 254, each of which

is spaced (FIG. 5) one from the other along the shaft 242, and each of which is equally spaced (FIG. 9) one from the other around the periphery of the cam shaft 242. Thus, like the indexing studs 246, 247, and 248, these cams 252, 253, and 254 are positioned for operation at 120-degree intervals. A bracket 255, secured to the base plate 74 and at a zone rearward of the cam shaft 242, fixedly carries three spaced-apart switches 103a, 203a, and 303a, aligned with and extending, respectively, under the plate cams 254, 253, and 252. As best seen in FIG. 9, the switch 103a is normally closed by the positioning of the cam 254 when the machine is at home; that is, prior to initiation of machine operation by the continuous cycle control lever 31. As described earlier, such switch 103a is included in the energizing circuit of the trip solenoid 103 (FIG. 13), thereby enabling the first machine cycle, which is the add cycle, of each machine operation to be initiated when the lever 31 is shifted rearwardly (FIG. 2). During the second half of such add cycle, the cam shaft 242 is rocked, as above described, 120 degrees clockwise (FIG. 9). In view of such rocking of the cam shaft 242, the switch 103a becomes opened as the cam 254 moves upwardly and away therefrom, thus preventing the next machine cycle from being initiated by the trip solenoid 103. At the same time, the cam 253 is moved downwardly to contact and close the switch 203a, this happening near the end of the machine cycle. Of course, the remaining cam 252 is also rocked along with the cam shaft 242, being moved to the position formerly held by the cam 253.

Referring to FIG. 13, upon the closing of the switch 203a, a circuit is completed for energizing a solenoid 203, which, through mechanism effected thereby, causes a non-add cycle of the machine to be initiated. As seen in FIG. 5, such solenoid 203 is herein illustrated as being secured to the base plate 74, at a zone approximately central of the machine, and having its forwardly-extending core member 204 operably interconnect, by means of a downwardly-extending link 265, a control lever 266 rockably mounted on the base plate 74. A spring 268, extending between the lever 266 and the machine rear base plate 73, normally urges the control lever 266 counter-clockwise about its pivot bolt 269 a distance determined by a base plate stop stud 270. When so positioned, which is the case until the solenoid 203 becomes energized, an outer cam portion 267 of the lever 266 (FIGS. 4 and 5) is located substantially behind an inwardly-directed stud 272 of the usual latch plate 271 rotatable about the machine right vertical frame plate stud 273.

Although the general construction of the calculating machine type of operation control mechanism embodied in the present invention is admirably described in United States Letters Patent to Harry L. Lambert No. 2,654,537, in order to assure a thorough understanding of the present machine cycle initiated by the solenoid 203, which is the second, or non-add, cycle of the machine operation initiated initially by the lever 31, pertinent mechanism thereof will likewise be described herein. Referring to FIG. 3, pivotally mounted on the main trip lever 82 is a bell crank 275, which has an upwardly-extending arm 276, normally urged into engagement with the upwardly-extending arm of the lever 82 by a spring 277. Thus, under normal operating conditions, the rearwardly-extending arm of the bell crank 275 operates as a rearward arm of the trip lever 82 and can therefore be actuated to rock the trip lever 82 clockwise. A stud 278 on the bell crank 275 can be engaged by a forward extension 280 (FIGS. 3 and 4) of the usual non-add and total lever latch 279, pivoted on a stud 282, which extends from the right plate 118 of the keyboard to depress the free end of the rearwardly-extending arm of the bell crank 275 and rock the trip lever 82 clockwise to initiate a machine cycle. This rocking of the trip lever 82, as above described, causes the link 278 to be shifted forwardly, in turn, rocking the trip lever 75 counter-clockwise to remove the trip

latch 49 from under the ear 42 of the three-armed lever 41.

Referring to FIG. 4, a non-add lever 283 is rockably mounted on the machine cross rod 143 and has pivoted thereto the upper end of a non-add link 284, the lower end of which is pivoted to the above-mentioned latch plate 271. A spring 285, extending from the link 284 and engaging a lower frame plate stud, normally urges the latch plate 271 counter-clockwise about its pivot 273, thereby presenting a latch-retaining plate 286, operably associated with the latch plate 271, in blocking relation with a rearwardly-extending flange 281 of the non-add and total lever latch 279. As seen in FIGS. 3 and 4, a spring 287 yieldingly urges the non-add and total lever latch 279 counter-clockwise about its pivot 282.

With such construction, upon the energization of the solenoid 203, the control lever 266 is thereby rocked clockwise about its pivot bolt 269 (FIG. 5), in turn, and by means of its outer cam portion 267, rocking the latch plate 271 clockwise about its pivot 273 (FIG. 4). As such latch plate 271 is rocked, its associated latch-retaining plate 286 is removed from blocking relation with the flange 281, thereby allowing the non-add and total lever latch 279 to be moved to a latching position under urging of the spring 287. As the latch 279 is thus moved, its forward arm 280 initiates a cycle of operation of the machine as explained earlier herein. Simultaneously therewith, the latch plate 271 shifts the non-add link 284 upwardly to condition the machine for a non-add operation in the manner fully explained in the United States patent to Heber C. Peters No. 1,386,021. Again, during such machine cycle, the cam shaft 242 is rocked (FIG. 9) an additional 120 degrees. During such rocking of the cam shaft 242, its drum cam 251 is likewise rocked, causing the control arm 136 to be rocked clockwise (FIG. 5), in turn, and through the control link 141, shifting the stop bars 122 from their normal alignment with the digit keys 25. Also, during such rocking of the cam shaft 242, its plate cam 253 moves away from the closed switch 203a, permitting it to open, while its plate cam 252 moves downwardly to contact and close the switch 303a. Its remaining cam, 254, is rocked to the position formerly held by the cam 252; that is, in the position for closing its switch 103a near the end of the next rocking movement of the cam shaft 242. In view of the immediate opening of the switch 92, at the very beginning of such non-add machine cycle, the circuit to the solenoid 203 is broken, and the control lever 266 is permitted to be returned to its normal position under urging of the spring 268. As best seen in FIG. 4, the non-add and total lever latch 279 retains the parts associated therewith in their moved positions until the usual roller 288 (FIG. 3) on the full-stroke sector 107 engages a by-pass pawl 289 on the latch 279 soon after the beginning of the return stroke of the sector 107, and rocks the latch 279 clockwise to move its flange 281 from latching relation with the latch-retaining plate 286, thereby releasing the trip lever 82 and allowing the spring 285 to return the non-add link 284 and parts affected thereby to their normal positions.

As seen in FIG. 13, upon the closing of the switch 303a, a circuit is now completed for energizing a solenoid 303, which, through mechanism actuated thereby, causes a sub-total cycle of the machine to be initiated. Referring to FIG. 5, such solenoid 303 is herein illustrated as being also secured to the base plate 74, adjacent the non-add solenoid 203, and having its rearwardly-extending core member 304 pivotally connected to an arm 306 secured to a sub-total trip shaft 305. This shaft 305 is journaled between the machine right frame plate 80 and an upstanding bracket 307 secured to the rear base plate 73. As seen in FIG. 3, a second arm 308 is secured to the shaft 305, on the outer side of the frame plate 80, and, by means of a link 309, extending between pivot studs 310 and 311, the shaft 305 is operably interconnected with a sub-total latch arm 312, rotatable about an upper, right vertical

frame plate bolt 313. A spring 314, stretched between the latch arm 312 and the shaft 169, yieldingly urges the latch arm 312 counter-clockwise to normally present an upper shoulder 315 thereof immediately behind a stud 317 carried by a sub-total trip arm 316, rockably mounted on a frame plate stud 319. An upper end portion 318 of the trip arm 316 is provided with gear teeth in constant mesh with like gear teeth provided on an arm 320 secured to the shaft 165. By means of a strong spring 321, extending between the arm 320 and a forward frame plate stud 322, the shaft 165 is cocked for a clockwise movement, being restrained from such movement in view of the normal latching of the trip arm 316 by the latch arm 312. In accordance with such construction, upon the energization of the sub-total solenoid, as above described, the latch arm 312 is rocked clockwise as the trip shaft 305 is rocked counter-clockwise, thereby removing the shoulder 315 of such latch arm 312 from behind the stud 317 and permitting the shaft 165 to be immediately rocked clockwise under the urge of the spring 321. In view of such gear teeth arrangement between the trip arm 316 and the shaft arm 320, the trip arm 316 is caused to be rocked counter-clockwise about its pivot 319 and present its lower end portion adjacent a stud 323, extending outwardly from the machine drive link 106.

As seen in FIG. 4, a trip finger 324 is secured to the shaft 165, being positioned adjacent the machine right frame plate 80 and in alignment with an inwardly-directed stud 325 carried by an arm 326 secured to the total lever 28. As also seen in FIG. 4, the stud 325 is in alignment with the above-described right arm portion 163 of the bail 161, rockably mounted on the shaft 165. As best seen in FIG. 3, a second stud 327, extending outwardly from the total lever 28, is operably associated with an upper cam arm 329 of a record feed lever 328 rockably mounted on the outer side of the machine right frame plate 80 by means of a bolt 330. A turned-over end portion 331 of a rearwardly-extending major leg of the lever 328 is operably interconnected, by means of a link 333 extending between pivot studs 334 and 335, with the above-mentioned bell crank 202 (FIG. 8). A spring 336, extending between the lever 328 and an upper frame stud 337, normally urges such record feed lever 328 counter-clockwise for presenting the record feed blocking arm 196 (FIGS. 7 and 8) in the path of travel of the yoke 189.

With this construction, it is apparent that, upon the energization of the solenoid 303 and the resultant clockwise rocking of the shaft 165 thereby, the trip finger 324 will cause the total lever 28 to be rocked counter-clockwise about its pivot 169. This rocking of the lever 28, as set out in United States Letters Patent No. 1,854,875, to Nelson White, conditions the machine mechanism in the usual manner for causing a sub-total operation to be performed. As seen in FIGS. 4 and 7, such rocking of the lever 28, by means of the aligned stud 325 and bail arm 163, also causes the bail 161 to be rocked clockwise, thereby rocking the print control bail 176 from under the interponents 153 and enabling the printing operation to be performed during such sub-total machine operation. In addition, the lever stud 327 causes the record feed lever 328 to be rocked clockwise an amount sufficient to remove its associated blocking arm 196 from in front of the yoke 189, thereby enabling the record material to be spaced in the usual manner near the end of the machine cycle. Thus, such rocking of the total lever 28 conditions the machine mechanism for a sub-total operation to be performed when the machine is cycled, enables the amount accumulated in the totalizer mechanism to be printed on the record material during such sub-total operation, and enables the record material to be spaced at the end of such sub-total machine operation. In addition, the initial rocking of the total lever 28 causes the machine cycle to be initiated—that is, causes the trip latch 49 (FIG. 12) to be rocked from under the ear 42 of the three-armed lever 41 as above described.

Although the precise structure for actually tripping the machine for this third or sub-total machine cycle is also substantially like that disclosed in United States Letters Patent No. 2,654,537, which issued to Harry L. Lambert and to which reference may be had, a somewhat different mode of operation thereof is incorporated in the present invention. Therefore, an added description of the pertinent tripping mechanism is included herein to assure a thorough understanding of such mechanism as embodied in the instant invention.

Referring to FIG. 4, as the total lever 28 is rocked counter-clockwise, the upper end of a link 340 is thereby shifted rearwardly and upwardly, causing the link 340 to move upwardly and rock the usual total control bell crank 341 counter-clockwise about its pivot 342 and against the action of a spring 343. When such bell crank 341 is rocked, it pulls a link 344 rearwardly. This link 344 is pivotally connected at its forward end to an arm 345, which is rockably mounted on a stud 346 provided on the inside of the machine right frame plate 80. When such link 344 is pulled rearwardly, a stud 347 thereon, cooperating with the bifurcated lower end portion of a bell crank 348, causes the bell crank 348 to rock about the above-mentioned pivot stud 273. As the bell crank 348 is so rocked, a forwardly-extending finger thereof is moved from above to below the flange 281 of the non-add and total lever latch 279. This movement of the bell crank 348 will also cause a stud thereon (illustrated in FIG. 4 but not designated by a specific reference numeral) to engage the latch-retaining plate 286 and rock that plate also about the stud 273 to remove its finger portion from blocking relation with the flange 281, thereby allowing the spring 287 to rock the latch 279 counter-clockwise about its pivot 282. The latch 279, when thus rocked, moves the flange 281 over the finger of the bell crank 348, thereby retaining the bell crank 348 and the total lever 28 in their moved positions. Also, in the movement of the non-add and total lever latch 279 to its latched position, its forward extension 280 engages the stud 278 and rocks the machine main trip lever 82 (FIG. 3) clockwise, thus initiating a cycle of operation of the machine in the manner explained earlier herein in relation to the second or non-add machine cycle included in the machine operation. At the very beginning of such sub-total cycle, the switch 92 is again opened to deenergize the solenoid 303. Upon this happening, the spring 314 attempts to return the shaft 305 and its associated members to their normal positions, being restrained from so doing in view of the upper, rear surface of the latch 312 now abutting the stud 317 as shifted by the spring 321.

As above described, the usual full-stroke sector 167 is oscillated forwardly and then rearwardly during each machine cycle. Soon after the beginning of the forward stroke of the sector 167, the stud 323 on the link 106 engages the lower end of the trip arm 316 and rocks that arm clockwise a distance sufficient to enable the spring 314 to rock the arm 312 counter-clockwise (FIG. 3) for again latching the arm 316 in its normal position—that is, with the stud 317 located behind the shoulder 315, as illustrated in FIG. 3. This rocking and latching of the arm 316 again cocks the shaft 165 as the spring 321 is tensioned, thereby returning the trip finger 324 (FIG. 4) back to its normal position. Again, the non-add and total lever latch 279 retains the parts associated therewith in their moved positions until the roller 288 (FIG. 3) engages the by-pass pawl 289, soon after the beginning of the return stroke of the sector 167, and rocks the latch 279 clockwise (FIG. 4) to move its flange 281 out of latching relation with the bell crank 348, thereby allowing the spring 343 to return the total lever 28 and parts connected thereto to their normal positions. Upon such return to home or normal position of the lever 28, the bail 161, with its associated mechanism, is returned to its normal, print-blocking position under urge of the spring 164 (FIG. 7). Simultaneously therewith, the record feed lever 328, with its asso-

ciated mechanism, is returned to its normal, record-feed-blocking position under urge of the spring 336 (FIG. 3). Also, during the second half of such sub-total machine cycle, the cam shaft 242 is again rocked 120 degrees by the drive pawl 235. This rocking of the cam shaft 242, along with prior rocking movements thereof during the above-mentioned add and non-add machine cycles, presents a complete revolution thereof, whereupon, as illustrated in FIG. 9, the switch 103a is again returned to its normally closed condition, while the switches 203a and 303a are maintained in open conditions.

In order to assure an accurate and positive positioning of the cam shaft 242 in this instance—that is, after it has been rocked 120 degrees by the drive pawl 235 during the above-described sub-total machine cycle—as well as after the first and second machine cycles of the machine operation, during each of which it is likewise rocked by the drive pawl 235, an aligning mechanism is included in the basic structure of the cycle control mechanism of the instant invention. As seen in FIG. 5, a detent wheel 256, herein illustrated as being positioned adjacent the left end of the cam shaft 242 and on the outer side of the base plate bracket 232, is secured to the cam shaft 242. This wheel 256, as seen in FIG. 9, is provided with three peripheral notches, like the notch 257, equally spaced one from another and in radial alignment with both the switch-actuating plate cams 252, 253, and 254 and the cam-shaft-indexing studs 246, 247, and 248. Operably associated with such wheel 256 is a horizontally-disposed stud 291, carried by a forwardly and upwardly extending arm of a detent lever 290, which, as best seen in FIG. 9, is rockably mounted on the rock shaft 230. By means of a spring 292, stretched between the lever 290 and a rearwardly positioned base plate stud 293, the lever 290 is yieldingly urged counter-clockwise to present its stud 291 in constant abutment with the periphery of the detent wheel 256, thereby assuring the desired positioning of the cam shaft 242 in each instance as a detent wheel notch 257 becomes aligned with and receives therein the stud 291.

Although the cycle control structure thus far described has been related to a single, three-cycle machine operation as initiated by the continuous cycle control lever 31, being done so herein for the sake of clarity, mechanism is associated with the above-mentioned control knob 29 permitting a selected number of such multiple-cycle machine operations to be performed, one after another, with the machine automatically coming to rest after the last cycle of the last machine operation has been completed. Referring to FIGS. 5 and 9, a single gear tooth 258 is secured to the detent wheel 256, being spaced a distance to the left thereof and extending radially outwardly from the outermost end of the cam shaft 242. This tooth 258, as best seen in FIG. 9, is operably associated with a large gear 295, rotatably carried by the rock shaft 230. A small gear 296, secured to the gear 295 and spaced a distance to the left thereof, is maintained in constant mesh with a third gear 261, secured to the innermost end of a short shaft 260, rotatably carried by the machine left vertical frame plate 40. This shaft 260, hereinafter referred to as a control shaft, is axially aligned with the cam shaft 242 and is selectively rotated by means of the control knob 29, which, as seen in FIG. 5, is secured to the outermost end thereof. Adjacent the inner surface of the machine frame plate 40, at a spaced distance to the left of the gear 261, the control shaft 260 is provided with a fixed cam 262, having an outwardly-extending abutment or protuberance 263, radially aligned with the "0" position as indicated on the control knob 29. Also aligned with the "0" position on the control knob 29 is a latch release stud 212 (FIGS. 2 and 5) extending inwardly from the minor length 210 of the switch latch 207 and lying normally in the path of travel of the cam abutment 263. As seen in FIG. 11, an aligning pawl 298 is yieldingly urged counter-clockwise, by means of a spring 300, about the shaft 224 to position a rearward, toothed end 299 thereof in constant association with the gear 295, rotatably carried by the rock shaft 230.

In accordance with such construction, the control knob 29 may be manually set for causing a selected number of the above-described three-cycle machine operations to be performed. Upon the setting of such knob 29 to the desired number of operations, from one to sixty as indicated thereon, the cam 262 is likewise set in accordance therewith. This setting of the cam 262, as best seen in FIG. 11, removes its abutment 263 from its normal alignment with the release stud 212 and positions it a distance therefrom corresponding to the movement of the control knob 29. As described earlier in the specification, when the machine is operated by the rearward shifting of the lever 31, such lever 31 becomes latched in its shifted position as the switch latch shoulder 209 falls behind the lower stud 206 thereof. Upon such latching of the lever 31, the switch 94 is retained in a closed condition to enable, as above described, the add, the non-add, and the sub-total machine cycles to be performed, one after another. Near the end of such sub-total cycle, the gear tooth 258, which has been rocked 360 degrees along with the cam shaft 242, contacts and rocks the large gear 295 a distance equal to approximately one tooth thereof. Upon such rocking of the gear 295, its associated gear 296 likewise rocks the gear 261 to index the control knob 29 that distance toward its home, or "0" position. Such indexing of the control knob 29 is best seen in FIG. 2, where the cam abutment 263 is thereby rocked counter-clockwise the one-tooth distance toward the latch release stud 212. This operation is continued until the control knob 29 is indexed back to its "0" position, at which time the cam abutment 263 contacts the release stud 212 and rocks the switch latch 207 counter-clockwise about its pivot 211 a distance sufficient to release the lever 31, which may then be returned to its unoperated position under urge of the spring 191. Upon this happening, the switch 94 is permitted to open and prevent a further machine operation from being initiated.

Machine Operation

In view of the fact that a somewhat detailed mode of operation is included with the specific description of the various mechanisms employed in the instant invention, the following discussion is included herein as a general, overall summary of the machine operation. In essence, and without going into any great extent of detail, it may be stated generally that the present invention enables an item amount to be repeatedly entered into a calculating machine totalizer mechanism with intervening totalizer reading and printing operations being performed, all without affecting, in any manner, the item amount as initially set up on the machine keyboard.

To effectively illustrate the general operation of such a machine, it is herein assumed, as an example of a typical machine operation, that an amount of 125 is initially set up on the digit keys 25 (FIG. 1) and the control knob 29 is manually rocked from its "0" position and set to its number 4 position. The continuous cycle control lever 31 may then be actuated for closing the switch 94, which, along with the current supply line switch 92, which is closed when the machine is at home, completes the necessary circuits for initiating one machine cycle after another until the overall operation is completed.

Referring to FIG. 13, upon the closing of the switch 94, a circuit is immediately completed through the normally closed cam shaft switch 103a for energizing the add solenoid 103. This solenoid 103, when energized, causes the first cycle of the first machine operation to be initiated, which is an add machine cycle wherein the illustrative amount of 125 is added into the totalizer mechanism of the machine. During such cycle, the machine stop bars 122 are stopped, in the usual manner, by the depressed digit keys representing the amount to be entered into the machine. In view of the normal positioning of

the print control bail 176 (FIG. 7), a printing operation is not performed during such cycle. Also, in view of the normal positioning of the record feed blocking arm 196 (FIG. 8), the record material is not spaced at the end of such cycle. As above described, the machine cam shaft 242 is rocked 120 degrees during the second half of such machine cycle, thereby opening the switch 103a and closing the switch 203a.

Upon the closing of the switch 203a and the return to home of the machine drive mechanism, thereby closing the switch 92, a circuit is completed for energizing the non-add solenoid 203 (FIG. 13). Such solenoid 203, when energized, causes a second machine cycle to be initiated for conditioning the machine for the third or totalizer-reading cycle of the machine operation. In this instance, the stop bars 122 are again stopped by the depressed digit keys during their forward excursion, but, as adequately set out in the reference patents, that amount is not again entered into the totalizer mechanism. Again, the cam shaft 242 is rocked during the second half of such machine cycle for now opening the switch 203a and closing the switch 303a. Also, during such rocking movement of the cam shaft 242, the drum cam 251, secured thereto, actuates the control arm 136, as above described, to shift the stop bars 122 from under their respective denominational rows of digit keys 25.

Referring further to FIG. 13, upon the return to home of the machine drive mechanism, the switch 303a being now closed, a circuit is completed for energizing the sub-total solenoid 303, which, as set out in detail in the specification, rocks the total lever 28 counter-clockwise (FIG. 4) to cause the third and final cycle of the machine operation to be initiated. As seen in FIGS. 4 and 7, upon such rocking of the total lever 28, the print control bail 176 is rocked downwardly from its normal blocking position, thereby permitting the totalizer-contained amount of 125 to be recorded at a first print-receiving line of the record material during such machine cycle. Such recording of the totalizer-contained amount is illustrated in FIG. 15, where a journal-type record material may be assumed as having been wrapped around the printing platen 24 of the machine. In view of the fact that the stop bars 122 have been shifted as above described, they are now stopped during their forward movement in accordance with the amount contained in the totalizer mechanism rather than by the depressed digit keys representing only the item amount initially entered into the machine. As seen in FIG. 3, the record feed lever 328 is also rocked by the total lever 28, thereby removing the record-feed-blocking arm 196 (FIG. 8) from the path of travel of the usual record-feeding yoke 189, and permitting the record material to be spaced to a second print-receiving line at the end of such machine cycle. As above described, the total lever 28 and its associated mechanisms are again returned to their normal positions near the end of the machine cycle. Referring now to FIG. 5, the cam shaft 242 is again rocked during the second half of such sub-total machine cycle, opening the switch 303a and again closing the switch 103a. At the same time, the drum cam 251 actuates the control arm 136 for causing the stop bars 122 to be returned to their normal positions immediately below the denominational rows of digit keys 25. Referring further to FIG. 5, along with FIG. 9, the gear tooth 258, which has now been rocked its full 360-degree movement along with the cam shaft 242, turns the large gear 295 a distance representing approximately a one-tooth movement. Such gear 295, through its associated gear 296, transfers such movement to the control shaft 260 and thereby indexes the control knob 29 back to its number 3 position. As best seen in FIG. 2, such return indexing of the control knob 29 is in a counter-clockwise direction, with the cam abutment 263 being moved toward the latch release stud 212.

In view of the fact that the switch 94 is retained in a closed condition at the end of such machine operation,

a second and like machine operation is immediately initiated as the circuit is again completed (FIG. 13) for energizing the add solenoid 103. During such machine cycle, an additional amount of 125 is entered into the totalizer mechanism of the machine, but such amount is not printed on the record material, and the record material itself is not spaced during such machine cycle. Again, the non-add machine cycle is initiated as the solenoid 203 becomes energized, thereby again shifting the stop bars 122 from alignment with the rows of digit keys 25. At the end of such non-add machine cycle, the solenoid 303 becomes energized to initiate the sub-total machine cycle and cause the accumulative amount of 250, as now contained in the totalizer mechanism, to be printed at the second print-receiving line of the record material (FIG. 15), and such material then spaced to a third print-receiving line near the end of the machine cycle. Against, the control knob 29 is indexed counter-clockwise at the end of the cycle (FIG. 2) back to its number 2 position.

Since the switch 94 remains closed at the end of the second machine operation, a third and like machine operation is immediately initiated as the solenoid 103 is permitted to be energized. During such machine operation, the digit keyboard amount of 125 is again entered into the machine totalizer mechanism, the stop bars 122 are again shifted in relation to the denominational rows of digit keys 25, and the accumulated amount of 375 is read from the totalizer mechanism and printed at the third print-receiving line of the record material (FIG. 15) prior to its being spaced to a fourth print-receiving line near the end of the machine operation. At the end of such operation, the control knob 29 is again indexed, as above described, being thereby returned to its number 1 position. At this time, a further machine operation is initiated, as the switch 94 remains closed to complete the circuit to the add solenoid 103. Thus, the amount of 125 is again added into the totalizer mechanism during the first cycle of the machine operation, the stop bars 122 are again shifted from under the digit keys during the second cycle thereof, and the accumulated amount now contained in the totalizer mechanism, being 500, is, as further illustrated in FIG. 15, recorded at such fourth print-receiving line of the record material prior to the stop bars 122 being returned under the digit keys 25, and the record material again spaced to a fifth print-receiving line (FIG. 15), during the third and final cycle of the fourth machine operation. In the manner described above, the control knob 29 is once more indexed at the end of this machine operation. Referring to FIGS. 2 and 11, such indexing of the control knob 29 causes the cam abutment 263 to now contact and rock the stud 212, thereby releasing the lever stud 206 from behind the shoulder 209 of the switch latch 207 and permitting the lever 31 to be returned to its forward, or unoperated, position under the urge of the spring 101. Upon this happening, the switch 94 is permitted to open and cause the machine to come to rest, as the control knob 29 is now returned to its "0," or starting, position.

As above described, the stop control key 33 may be depressed at any time during a machine operation. When depressed, such key releases the lever 31 from its latched condition, thereby causing the machine to come to rest at the end of the particular cycle being then performed. Machine cycling may, of course, be resumed immediately, or at any time thereafter, upon the return of the lever 31 to its shifted position.

As disclosed, the preferred embodiment of the present invention enables a selected amount to be entered only additively into the totalizer mechanism, facilitating an increasing balance (FIG. 15) or consecutive number (FIG. 16) type of machine application. Looking to FIG. 16, where the record material illustrated is in the form of a strip of tickets and the like, it is seen that, 75 should the above-set-out representative item amount of

"125" on the machine digit keys 25 be replaced by an item amount of "1," the resultant printing will be a consecutive numbering operation, either for each of the tickets of FIG. 16, or, as a further example, for each of the print-receiving lines of FIG. 15. While such increasing balance and consecutive numbering machine applications are those permitted under the preferred embodiment of the present invention, it is apparent that such invention may also be easily adapted for a declining balance type of machine application. In this regard, the only changes necessary in the machine construction would be to replace the herein-disclosed add mechanism with subtract mechanism, thereby causing an amount to be entered subtractively rather than additively into the totalizer mechanism during the first cycle of each machine operation. With such construction, a desired amount may be initially entered into the totalizing mechanism under control of the add motor bar 26, and then, through continuous cycle machine operations initiated by the lever 31, be effectively reduced by desired increments as set up on the digit keys 25.

It is also apparent that slight changes in the disclosed mechanism may enable the total lever 2 to be rocked clockwise (FIG. 4) rather than counter-clockwise, thereby initiating a total cycle rather than the sub-total cycle as disclosed herein for each machine operation. Under such a machine cycle, which is the third cycle of each machine operation, the amount contained in the totalizer mechanism would be withdrawn therefrom and such mechanism reset to its zero position at the end of the cycle. With such construction, it is apparent that the instant invention may be adapted for a digit repeat type of machine application, such as that needed for printing a common number on a plurality of tickets, for printing an account number on various banking instruments, and even printing a common cost on a predetermined number of price tags or labels. In this instance, the digit amount, as set up on the keyboard, would be entered into the totalizer mechanism during each machine operation and then withdrawn therefrom as it is printed on the record material, such operation being continuously performed in accordance with the setting of the control knob 29.

While the forms of mechanism shown and described herein are admirably adapted to fulfill the objects primarily stated, it is to be understood that it is not intended to confine the invention to the forms or embodiments disclosed herein, for it is susceptible of embodiments in various other forms, all coming within the scope and spirit of the invention. Therefore, I desire not to be limited to that precise form of the invention beyond the limitations which may be imposed by the following claims.

What is claimed is:

1. A calculating machine having a totalizer mechanism for receiving and accumulating digit amounts; a differential mechanism for setting said totalizer mechanism in accordance with digit amounts to be entered therein and being set by said totalizer mechanism in accordance with accumulated amounts contained therein; a plurality of selectively operable digit keys normally cooperating with said differential mechanism in order that said differential mechanism may be set by operated digit keys and in turn set the totalizer mechanism in accordance therewith; and means for shifting said differential mechanism from cooperative relation with said digit keys in order that said differential mechanism may be set by the totalizer mechanism without disturbing and without being affected by the operated digit keys.

2. The machine of claim 1, including a cyclically operable main drive means; means for initiating a multiple cycle operation of said drive means; means actuating said differential mechanism during each cycle of said drive means; and machine cycle control mechanism for causing said totalizer mechanism to be set by said differential mechanism when actuated during one cycle of said drive means and causing said differential mechanism to be set

by the totalizer mechanism when actuated during another cycle of said drive means.

3. In a calculating machine, the combination of drive means for providing a machine cycle of operation; a totalizer mechanism for receiving and accumulating digit amounts entered into the machine; a differential mechanism cooperating with said totalizer mechanism for entering digit amounts therein and reading accumulated amounts therefrom; said differential mechanism setting the totalizer mechanism when entering digit amounts therein and being set by the totalizer mechanism when reading accumulated amounts therefrom; means for initiating a machine cycle of operation; means whereby said differential mechanism is actuated during each machine cycle of operation; a keyboard having a plurality of digit keys selectively settable for cooperating with said differential mechanism and controlling the movement thereof when actuated for entering digit amounts into the totalizer mechanism; a non-add control mechanism for controlling the cooperation of said totalizer mechanism and said differential mechanism to prevent the entering of digit amounts into the totalizer mechanism; a sub-total control mechanism for controlling the cooperation of said totalizer mechanism and said differential mechanism to enable said totalizer mechanism to control the movement of the differential mechanism to read the accumulated amount contained therein; a printer mechanism settable for printing an amount corresponding to the movement of the differential mechanism during each machine cycle of operation; a non-print control mechanism for preventing the printer mechanism from printing the amount set by the differential mechanism; and a cyclically operable multiple-cycle control means for causing a first machine cycle to add a digit amount as set on the machine keyboard into the totalizer mechanism with a non-printing of such amount, a second machine cycle to non-add the totalizer mechanism to prevent such keyboard digit amount from being entered therein, non-print the amount thereof, and shift the differential mechanism from cooperative relation with said digit keys, and a third machine cycle to sub-total the totalizer mechanism and print the accumulated amount read therefrom while keeping the digit key setting on the machine keyboard.

4. The machine of claim 3, including a selectively settable control means enabling a predetermined number of such multiple-cycle machine operations to be performed.

5. In a calculating machine, the combination of a drive means for providing a machine cycle of operation; a totalizer mechanism for receiving and accumulating digit amounts entered into the machine; a differential mechanism cooperating with said totalizer mechanism for entering digit amounts into the totalizer mechanism and reading accumulated amounts contained in the totalizer mechanism; said differential mechanism setting the totalizer mechanism when entering digit amounts therein and being set by the totalizer mechanism when reading accumulated amounts therefrom; means for initiating a machine cycle of operation; means whereby said differential mechanism is actuated during each machine cycle of operation; a keyboard having a plurality of selectively operable digit keys, said keys, when operated, cooperating with said differential mechanism and controlling the movement thereof when actuated for entering digit amounts into the totalizer mechanism; a sub-total control mechanism for controlling the cooperation of said totalizer mechanism and said differential mechanism to enable said totalizer mechanism to control the movement of the differential mechanism to read the accumulated amount contained therein; a printer mechanism settable for printing an amount corresponding with the movement of the differential mechanism during each machine cycle of operation; a non-print control mechanism normally preventing the printer mechanism from printing the amount set by the movement of the differential mechanism; a cyclically operable, multiple-cycle control means for causing one machine cycle to add

a digit amount into the totalizer mechanism under control of operated digit keys and with a non-printing of such amount, and another machine cycle to sub-total the totalizer mechanism and print the accumulated amount read therefrom while digit keys remain operated on the machine keyboard; and selectively settable control means provided for enabling a predetermined number of such multiple-cycle machine operations to be performed.

6. The machine of claim 5, including a non-add control mechanism for controlling the cooperation of said totalizer mechanism and said differential mechanism to prevent the entering of digit amounts into the totalizer mechanism; said multiple-cycle control means provides an intermediate machine cycle under control of said non-add control mechanism and with a non-printing of the digit amount set up in the printer mechanism by the differential mechanism during such cycle; said multiple-cycle control means includes mechanism for shifting said differential mechanism from cooperative relation with operated digit keys during such non-add machine cycle, thereby enabling said differential mechanism, when actuated during the sub-total machine cycle, to be set by the totalizer mechanism; and said sub-total control mechanism includes means for releasing the non-print control mechanism during such sub-total machine cycle in order that the printer mechanism may print an amount corresponding to the setting of the differential mechanism by the totalizer mechanism.

7. In a machine of the class described, the combination of a cyclically operable machine drive means; a totalizer mechanism for receiving and accumulating digit amounts entered into the machine; a differential mechanism for entering digit amounts into and reading accumulated amounts contained in the totalizer mechanism; said differential mechanism controlling the operation of the totalizer mechanism during digit entering cycles of said drive means, and being controlled by the operation of said totalizer mechanism during accumulated amount reading cycles of said drive means; amount entry control means settable into cooperative relation with the differential mechanism for controlling such mechanism in accordance with each digit amount being entered into the totalizer mechanism; and machine cycle control mechanism for causing the differential mechanism to be removed from cooperative relation with the set amount entry control means in order that the accumulated amount contained in the totalizer mechanism may be read by the differential mechanism without disturbing the setting of the amount entry control means.

8. The machine of claim 7, in which said amount entry control means comprises a plurality of rows of selectively operable digit keys, each key having an abutment movable to digit entering position when operated; said differential mechanism includes a plurality of stop bars, each of which is normally aligned with the abutments of a respective row of digit keys; means whereby the stop bars are given a forward movement during each cycle of said drive means; said bars being stopped by the abutments of operated keys during digit entering cycles of said drive means; and said cycle control mechanism includes means for shifting each of said stop bars from alignment with said digit key abutments so that said stop bars, when given a forward movement, are not stopped by the abutments of operated digit keys.

9. The machine of claim 8, in which said shifting means comprises a drive pawl; means whereby said drive pawl is given an oscillating movement during each cycle of said drive means; a stop bar shifting member operably associated with said drive pawl; means interconnecting said shifting member with said stop bars; and a cycle initiating member for causing an operation of said drive means, whereupon said drive pawl actuates said shifting member, which shifts said stop bars from alignment with said digit key abutments.

10. In a machine of the class described, the combination of a cyclically operable machine drive means; a

totalizer mechanism for receiving and accumulating digit amounts entered into the machine; a differential mechanism for entering digit amounts into and reading accumulative amounts contained in the totalizer mechanism; said differential mechanism controlling the operation of the totalizer mechanism during digit entering cycles of said drive means, and being controlled by the operation of said totalizer mechanism during accumulated amount reading cycles of said drive means; means normally aligned with the differential mechanism for setting such mechanism in accordance with each digit amount to be entered in the totalizer mechanism; means for shifting the differential mechanism for alignment with the setting means; and means for initiating an operation of said drive means, during which the shifting means causes the differential mechanism to be shifted from alignment with the setting means in order that the differential mechanism may be operated by the totalizer mechanism without being affected by the setting means.

20 11. The machine of claim 10, in which said setting means comprises a plurality of rows of selectively operable digit keys; said differential mechanism includes a plurality of shiftable stop bars, each of which is normally aligned with a respective row of digit keys; means whereby said stop bars are given a forward movement during each cycle of said drive means; said stop bars being stopped by operated digit keys when moved forwardly during digit entering cycles of said drive means; and said shifting means, during each drive means operation initiated by said initiating means, shifting said stop bars from alignment with said digit keys, whereby said stop bars, when moved forwardly, are not affected by operated digit keys.

12. The machine of claim 11, in which said stop bars normally extend immediately under the rows of digit keys; said digit keys, when operated, present abutments in the path of travel of said stop bars for selectively stopping said bars when moved forwardly thereunder; and said shifting means laterally shifts said stop bars from under said rows of digit keys, thereby enabling said stop bars to travel past the abutments of operated digit keys.

13. The machine of claim 11, in which said shifting means comprises a drive pawl; means whereby said drive pawl is given an oscillating movement during each cycle of said drive means; a stop bar shifting member operably associated with said drive pawl; means interconnecting said shifting member with said stop bars; and a manually shiftable member for initiating an operation of said drive means, whereupon said drive pawl, during its oscillating movement, actuates said shifting member which, through said interconnecting means, shifts said stop bars from alignment with said digit keys.

14. The machine of claim 13, including a series of racks associated with said totalizer mechanism; a plurality of diverging levers supporting said racks and pivotally carrying the rear end of each stop bar, one lever for each row of digit keys and rockably mounted therebehind; a shiftable comb member supporting the front end of each stop bar and guiding said bar during forward movement thereof; and said interconnecting means extends between said shifting member and said comb member for shifting said comb member, which, in turn, carries the front end of each stop bar therewith while rocking the rear end thereof at its pivot connection.

15. The machine of claim 13, including means for causing a multiple-cycle operation of said drive means during each machine operation initiated by said shiftable member, said means comprising a cam shaft having a drive member aligned with said drive pawl; a plurality of switch-actuating cams secured to said cam shaft, each being equally spaced, one from another, around said cam shaft; a switch member operably associated with each actuating cam, one being closed with the remaining open in accordance with the positioning of said cams; a solenoid electrically interconnected with each switch member; means actuated by each solenoid for initiating a cycle of

operation of said drive means; means also actuated by each solenoid for causing a specific machine function to be performed during each machine cycle initiated thereby; and switch means being closed by the operation of said shiftable member for initiating a cycle of operation of said drive means through said one switch and associated solenoid; said drive pawl, when oscillated during such cycle, actuating said drive member and rocking said cam shaft an amount sufficient to enable said cams thereon to open said one switch member and close a remaining one of said switch members, thereby causing an additional cycle of operation to be initiated by the solenoid associated therewith.

16. The machine of claim 13, including means enabling a predetermined number of continuous drive means operations to be performed, said means comprising a latch member for retaining said shiftable member in an operated position when manually shifted for initiating an operation of said drive means; a control knob having a zero position settable from a home position to a selected digit position therefrom representing a desired number of machine operations to be performed; a cam-like member fixedly associated with said control knob and settable in accordance with the setting thereof, said member having a protuberance radially aligned with the zero position of said control knob; means operated during each machine cycle for indexing said control knob a one-digit movement from a set position toward said home position; and a latch member stud aligned with the home position and extending in the path of travel of said cam member protuberance; said cam member protuberance, when indexed from a set position back to home along with the control knob, engaging said stud and actuating said latch member for releasing the shiftable member from its operated position.

17. The machine of claim 14, in which said stop bars normally extend immediately under the rows of digit keys; said digit keys, when operated, present abutments in the path of travel of said stop bars for selectively stopping said bars and setting said racks in accordance with the operation thereof when said bars are moved forwardly thereunder; said comb member is shiftable carried by a supporting frame located forwardly of and normal to said rows of digit keys; and said comb member is longitudinally shiftable a distance along said supporting frame for laterally shifting the front ends of said stop bars a like distance from under the rows of digit keys, thereby enabling said stop bars to be moved forwardly in a path of travel not affected by the abutments of operated digit keys.

18. The machine of claim 15, in which there are three of said switch actuating cams rockable with said cam shaft; said solenoids include a first one for causing a digit entering machine cycle to be initiated, a second one for causing a non-add machine cycle to be initiated, and a third one for causing a totalizer reading machine cycle to be initiated; said one switch is associated with said first solenoid for initiating the digit entering machine cycle; and said drive pawl rocks said cam shaft one hundred and twenty degrees during the second half of each cycle of said drive means, whereby near the end of the digit entering machine cycle initiated by the first solenoid, said actuating cams open said one switch member and close a second one of said switch members for causing a non-add machine cycle to be initiated by the second solenoid associated therewith, and whereby near the end of such non-add machine cycle said cams open said second switch member and close a third one of said switch members for causing a totalizer reading machine cycle to be initiated by the third solenoid associated therewith.

19. The machine of claim 18, in which said stop bar shifting member is carried by and rocked with said cam shaft during each machine cycle; said shifting member, through said interconnecting means, shifts said stop bars from alignment with said digit keys when rocked during

the second or non-add machine cycle; and said shifting member, through said interconnecting means, returns said stop bars to alignment with said digit keys when rocked during the third or totalizer reading machine cycle, thereby causing said stop bars to be not affected by operated digit keys during the totalizer reading machine cycle and enabling said stop bars to be affected by operated digit keys during both the digit entering and non-add machine cycles.

20. The machine of claim 18, including means enabling a predetermined number of such multiple-cycle machine operations to be continuously performed, said means comprising a latch member for retaining said shiftable member in a switch-closing position when manually shifted for initiating an operation of said drive means; a shiftable member release stud carried by said latch member; a control shaft; a control knob secured to said control shaft and rockable from a home position to a selected digit position representing the desired number of machine operations to be performed; a cam member secured to said control shaft and settable in accordance with the rocking of said control knob, said cam member being operably aligned with said release stud; drive means carried by said control shaft; and cam shaft means operably associated with said drive means for rocking reversely said control knob and cam member a predetermined amount near the end of each totalizer reading machine cycle; said cam member, when so rocked during a machine operation returning the control knob from a set position to its home position, engaging said release stud and rocking said latch for enabling said shiftable member to be returned to a switch-opening position.

21. The machine of claim 18, including a printer mechanism being set for printing a digit amount in accordance with the movement of the differential mechanism during each cycle of said drive means; means normally positioned for restraining said printer mechanism from printing said digit amount during each cycle of said drive means; and means actuated by said third solenoid for removing said restraining means from its normal position in order that the digit amount contained in the totalizer mechanism may be printed during the totalizer reading machine cycle initiated by said third solenoid.

22. The machine of claim 19, in which said shifting member comprises a further cam member secured to said cam shaft; and said interconnecting means comprises a control arm and link continuously interconnecting said further cam member with said stop bars for shifting said stop bars in accordance with the rocking movement of the cam member.

23. The machine of claim 21, in which said printer mechanism comprises a plurality of print bars, each shiftable to a printing position in accordance with the forward movement of a respective stop bar; a print hammer aligned with each print bar, being cocked and latched for operation by a latch at the conclusion of a machine cycle in which it is operated; means actuated during each machine cycle for firing the print hammers; and an interponent extending between the actuated means and each hammer latch, and rockable into a latch releasing position upon the shifting of each print bar for rendering the actuated means effective to fire the hammer associated therewith; said restraining means is normally positioned in relation to each interponent for blocking the rocking movement thereof prior to the latch releasing position, thereby rendering the actuated means ineffective to fire the print hammer associated therewith; and said removing means causes said restraining means to be moved from such blocking position in relation to each interponent, thereby enabling each interponent to be rocked to its latch releasing position and render the actuated means effective to fire the hammer associated therewith.

24. The machine of claim 23, in which each interponent is yieldingly rocked from a non-releasing position

toward said releasing position simultaneously with the shifting of said stop bar; said restraining means comprises a print control bail normally rocked to a position intermediate said non-releasing and releasing position of said interponent, and in the path of such rocking movement thereof; and said removing means comprises a second bail operably interconnecting said print control bail with said third solenoid, whereby said third solenoid, when energized, rocks said print control bail from said intermediate position and out of the path of travel of said interponent.

25. In a machine of the class described, the combination of a cyclically operable machine drive means; a totalizer mechanism for receiving and accumulating digit amounts entered into the machine; a printer mechanism for printing accumulated digit amounts contained in the totalizer mechanism; a differential mechanism associated with both the totalizer mechanism and the printer mechanism, controlling the operation of the totalizer mechanism for entering digit amounts therein, and being controlled by the totalizer mechanism for setting the printer mecha-

nism in accordance with the accumulated amount contained therein; means for initiating digit entering and printer setting cycles of said drive means; a plurality of rows of selectively operable digit keys; a plurality of stop bars pivotally carried by said differential mechanism, each of which is normally aligned with and shiftable along a respective row of digit keys; said digit keys, when operated, cooperating with the aligned stop bars to determine the extent of movement of the differential mechanism during digit entering cycles of said drive means; and means for shifting said stop bars out of cooperative relation with the operated digit keys during printer setting cycles of said drive means, thereby enabling the differential mechanism to be operated by the totalizer mechanism without being affected by the operated digit keys.
